UNITED STATES PATENT OFFICE.

LIPA POLINKOWSKY, OF ANTWERP, BELGIUM, ASSIGNOR TO WESTERN ELECTRIC COMPANY, INCORPORATED, OF NEW YORK, N. Y., A CORPORATION OF NEW YORK.

AUTOMATIC TELEPHONE-EXCHANGE SYSTEM.

Application filed June 13, 1923. Serial No. 645,066.

To all whom it may concern:

Be it known that I, LIPA POLINKOWSKY, a citizen of Russia, residing at Antwerp, Belgium, have invented certain new and useful Improvements in Automatic Telephone-Exchange Systems, of which the following is a full, clear, concise, and exact description.

This invention relates to machine switching telephone exchange systems, and more particularly, to machine switching telephone systems of the full automatic type in which the automatic switches are controlled by means of a central office sender having registers upon which the designations of desired lines are recorded.

Registering mechanism for this purpose, in accordance with the usual practice, consists of a number of registers actuated by impulses transmitted from the calling subscriber's dial, these registers either returning to normal in response to the transmission of revertive impulses from the automatic switches, thus insuring the extent of movement of such switches or connecting up particular relays of a counting chain of relays for measuring the extent of movement of the switches.

It is the principal object of the present invention to provide an improved register mechanism of this character which will be simple and very flexible in operation permitting the establishment of calls of varying characteristics.

A feature of the invention is the provision of a registering mechanism adapted to record the designation of a desired line, a portion of which mechanism is divided into a primary and a secondary section. The primary section consists of a single register which registers the first digit dialed by the calling subscriber and through its setting selects one of a plurality of registers comprising the secondary section. The second digit dialed is then recorded by the particular secondary register selected.

A further feature of the invention provides for the positioning of the selected secondary register in the first or second portion of its bank in accordance with whether the first digit dialed was odd or even in value.

The remaining registers of the registering mechanism are arranged to record the

remaining digits of line designations and are set successively thereby. The registers of the secondary group are each provided with a number of banks of terminals which may be associated with a cross-connecting rack at which connections may be made to the counting relays of the sender. Such an arrangement permits great flexibility in the manner in which the automatic switches are controlled in accordance with the particular designation set up upon the registers.

A further feature of the invention relates to the provision of means whereby it is possible to initially operate an exchange system with a much smaller number of subscribers' lines than the ultimate capacity of the system, thereby eliminating certain group switching stages. This is accomplished by causing the registering mechanism to skip one or more switch controlling stages should the called line designation recorded on the registers thereof necessitate the employment of a less number of switching stages than the full number of stages provided for in its ultimate capacity.

A still further feature of the invention relates to means for stopping the selecting operation of the automatic switching apparatus at a definite switching stage before the final switching stage is reached, whereby connections such as to trunk lines leading to other exchanges may be selected in any desired number of switching stages, the selective operation of the switching apparatus being arrested at the end of the proper switching stage through means associated with the registering mechanism.

A further feature resides in the provision of means for automatically extending calls to a supervisory operator's position if designations of lines which do not exist are recorded upon the registers of the registering mechanism.

These and other features of the invention will more readily appear by reference to the following description considered in connection with the accompanying drawings.

Fig. 1 illustrates a subscriber's line, a first line finder, and at the bottom of the figure, a sender allotter individual to the link circuit of Fig. 2.

Fig. 2 shows a link circuit terminating at one end in a secondary line finder and at its other end in a first group selector.

Fig. 3 shows an incoming distant group selector.

Fig. 4 shows a third group selector.

Fig. 5 shows a final selector and one of the subscriber's lines terminating in the bank of the final selector.

Figs. 6 to 9, inclusive, taken together show the circuits of a central office register sender for controlling the setting of the selector switches. Of these figures Fig. 6 shows the primary or A code register and the register steering or progression switch. Fig. 7 shows the four secondary or B code registers. Fig. 8 shows the numerical registers and Fig. 9 shows the controlling and impulse measuring circuits of the sender.

Fig. 10 is a diagram illustrating the manner in which the several figures of the drawings should be arranged to form a complete circuit disclosure illustrating the invention.

The selector switches employed and illustrated in Figs. 1 to 5, inclusive, may be of the general type shown and described in the patent to Polinkowsky No. 1,193,053, issued August 1, 1916. The registering mechanism shown in Figs. 6 to 9, inclusive, is adapted to be controlled by means of a calling subscriber's dial such as illustrated diagrammatically at 100, Fig. 1, of the type which transmits upon each operation thereof, a number of impulses corresponding to the value of the digit dialed. Each register A, B¹, B², B³, B⁴, TH, H, T and U of Figs. 6, 7 and 8 consists of a plurality of wipers mounted upon a shaft which is adapted to be rotated by means of a stepping magnet operated by impulses transmitted thereto from a subscriber's dial. The register A in its several resting positions is arranged to select one of the four secondary registers B¹, B², B³ or B⁴. The register steering or progression switch RS is of the same general type as the registers and serves to progressively route the several series of impulses comprising a desired line designation to the several registers.

The sender mechanism shown in Fig. 9 comprises a controlling sequence switch 920 of the well known type, a group of eleven pairs of counting relays, a portion of which have been omitted, and various control relays, the functions of which will clearly appear hereinafter. The counting relays are connected to the banks of the numerical registers shown in Fig. 8 and to one side of a cross connecting rack 700 shown at the extreme right of Fig. 7 from which jumper connections may be extended as desired to the banks of the secondary registers of Fig. 7, and to the armature contacts of relays 716, 717 and 718. By the use of this rack the terminals engaged by the brushes of the secondary registers may be readily connected to different counting relays and the control of the automatic switches by the A and B

registers made very flexible. Other terminals on the rack appearing at the extreme left and extreme right of Fig. 7 may be cross connected to banks of the secondary registers as desired. The invention will be described in connection with one only of the many possible cross-connecting arrangements.

The system disclosed as embodied in the present invention will be best understood from a description of the operation thereof. For this purpose it will be assumed that the subscriber whose substation is designated at L desires a connection with a subscriber whose substation is designated at M, Fig. 5, and whose directory number is BY 5532. The calling subscriber upon removing his receiver from the switchhook establishes a circuit over the line loop for the line relay 101 extending through back contacts of the cut-off relay 107, thereby operating the line relay. With the line relay operated a potential is created on the test terminal 121 of the calling line, multiplied to the banks of all first line finders having access thereto. This potential is connected over a path extending from the terminal 121, through the resistance 102 to battery at the contact of relay 101. Relay 101 also establishes a circuit through the resistances 102 and 103 for the common starting relay 104, which in turn, establishes a circuit extending in parallel through the subgroup relay 106 and the peg count relay 105. If the number of subgroups of first line finders exceeds three, a second relay corresponding to 106 is also provided which is operated in parallel with relay 106. Relay 105, upon energizing, closes a circuit for the peg count meter 122. Relay 106 prepares a circuit for the subgroup relays 109, one of which is disclosed, which in turn, prepare circuits through the high resistance windings of test relays 114 and through the power magnets 111 of all idle line finders in the subgroups. If more than three line finders are provided in each subgroup, two relays corresponding to relay 109 are employed.

The circuit for the power magnet 111 of the line finder 150 disclosed may be traced from the outer right armature and contact of relay 109, through the power magnet 111, the armature and back contact of test relay 112 to battery, through the armature and back contact of disconnect relay 113. As soon as an idle line finder of the several which have been started finds the terminals of the calling line, the test relay 114 of such line finder becomes energized. It will be assumed that the line finder disclosed is the one that first finds the line and that the circuit for the test relay extends from battery connected to the test terminal 121, over the brush 110, the left high resistance winding of relay 114 to ground at the outer left

armature and contact of relay 109. Relay 114, upon energizing, connects its low resistance right-hand winding in parallel with its high resistance left hand winding for 5 the purpose of making the test terminal of the calling line busy to other finder switches. The circuit of the right hand winding extends through the winding, the armature and contact of the relay, the commutator 10 wiper 119 to ground until the brushes of the finder become properly centered upon the terminal of the calling line when direct connection to ground through the right hand winding is opened and the right hand 15 winding is maintained energized in series with the test relay 112. Relay 112 now becomes energized, opening the circuit of the power magnet 111 at its armature and back contact and at its front contact establishing a circuit extending from battery at 20 the armature and contact of relay 113, through the stop magnet 115 to ground through the winding of the common second line finder start relay 116.

25 With relay 116 energized, a circuit is established for relay 139, which at its armatures and contacts, closes circuits for starting a plurality of second line finders in search for the particular first line finder trunk now 30 connected with the calling line. It will be assumed that the line finder shown in Fig. 2 is the one that ultimately makes connection. The starting circuit for this line finder may 35 be traced from battery, through the outer right armature and contact of relay 139, the upper left and lower right contacts of cam 223, winding of relay 222, lower contact of cam 201 (1 to 3), armature and back contact of relay 234 to ground at the upper right 40 contact of cam 202 (1 to 2). Relay 224 is also energized in parallel therewith over a circuit extending from the upper right contact of cam 223 (1 to 3), winding of relay 224, upper contact of cam 200 to ground at the armature and back contact of relay 237. Relay 224 is maintained locked over its inner right armature until after sequence switch 220 leaves position 3. With relays 222 and 45 224 energized a circuit is closed for the power magnet 221 of the second line finder which may be traced from battery through this power magnet, the right contact of cam 203, the right armature and front contact of relay 222 to ground at the outer left 50 armature and front contact of relay 224. When the test brush 230 of the second line finder encounters potential upon the terminal 204 which was applied thereto through the operation of relay 112 from battery at the 55 armature and back contact of relay 113, over the armature and front contact of relay 112, the right armature and back contact of relay 113, through resistance 117, a circuit is completed for relay 234 which may be traced 60 from brush 230, the upper left contact of 65 cam 228, the right high resistance winding of relay 234, the inner left armature and front contact of relay 224 to ground at the upper left contact of cam 205 (18 $\frac{3}{4}$ to 1). Relay 234, upon energizing, connects its low 70 resistance left winding in parallel with its high resistance right winding for the purpose of altering the potential upon the test terminal 204 to prevent the other finders which are hunting for this terminal from 75 stopping thereon. The circuit over which the left winding of relay 234 is connected may be traced through the upper contacts of cam 228, the left winding of relay 234, armature and front contact of relay 234 to 80 ground at the upper right contact of cam 202 (1 to 2). At its armature and back contact relay 234 opens the circuit previously traced through the relay 222, which upon deenergizing, opens the circuit 85 of the power magnet 221. To insure that the second line finder will stop without overrunning the terminal of the selected trunk, a circuit is established for the stop magnet 225 extending from battery through the 90 winding of this magnet, the lower contacts of cam 206, the right armature and back contact of relay 222 to ground at the outer left armature and front contact of relay 224. A circuit is also established in parallel 95 therewith through the winding of sequence switch magnet 220, whereupon the sequence switch advances into position 3.

When the sequence switch passes position 2 a circuit is established for relay 207 which 100 may be traced from battery through the winding of this relay, the right contacts of cam 208, the outer left armature and back contact of relay 209 to ground at the lower contact of cam 210. Relay 207 establishes a circuit for relay 235 which may be traced from ground through the inner left armature and front contact of relay 207, the winding of relay 235, brush 238, brush 118 and 105 in parallel through the winding of cut off relay 107 of the calling line and message register magnet 108. The current flowing in this circuit while of sufficient strength to operate the cut off relay 107 and relay 235, 110 does not operate the message register 108. Relay 235, upon energizing in this circuit, establishes a locking circuit for relay 207 extending through its armature and front contact, outer left armature and back contact of relay 209 to ground at the lower contact of 115 cam 210. In addition to operating relay 235, relay 207 cuts the tip and ring conductors of the trunk circuit through to the battery supply coil 231 and relay 237, over the right contact of cam 213 and the upper contact of cam 212. Relay 237 now becomes 120 energized over the subscriber's line loop and at its armature and front contact completes the battery supply bridge through the winding of coil 257. As soon as the sequence switch 125

leaves position 2 the circuit of relay 234 is opened at the upper left contact of cam 228 and relay 234 unlocks, again closing at its armature and back contact a circuit for relay 222 which may be traced from battery through the lower contacts of cam 223, winding of relay 222, lower contact of cam 201, armature and back contact of relay 234 to ground at the contact of cam 130.

10 In position 3, of sequence switch 220, a circuit is established for the sender selecting sequence switch 120 which may be traced from battery through the magnet winding of switch 120, upper right contact of cam 211 (2½ to 3), lower contact of cam 201, armature and back contact of relay 234 and thence to ground as previously traced. The switch 120 continues to rotate until an idle sender is found when battery potential will 15 be encountered upon one of the contacts of the group of cams 124. It will be assumed that such an idle sender has its test lead connected to the lower contacts of cam 125 and that when these contacts are closed in position 1¾ to 2 of switch 120, a circuit is established from battery through the upper contact of cam 900, the lower contacts of cam 125, the right contacts of cam 214, the right winding of relay 234, contact of cam 123 (15/8) to ground at the right armature and back contact of relay 209. Relay 234, upon energizing, connects its low resistance left winding in parallel with its right winding, through the upper right contact of cam 214 (3 to 4), the right contact of cam 228 (1 to 4), the left winding armature and front of relay 234 to ground at the contact of cam 130. Through the connection of the low resistance winding 234 in parallel with the right high resistance winding the test potential is altered at the multiples of contacts of switch 120 to prevent the seizure of the sender which has been selected by other sender selector switches. With relay 45 234 energized the energizing circuits previously traced for relay 222 and the selector magnet 120 are opened and as soon as relay 222 becomes deenergized a circuit is established for advancing sequence switch 220 out of position 3 into position 4. This circuit may be traced from battery through the magnet winding of switch 220, the lower right contact of cam 206 (17 to 3), the right armature and back contact of relay 222 to ground at the outer left armature and front contact of relay 224.

50 As soon as the sequence switch 220 leaves position 3, relays 237 and 224 become deenergized. With sequence switch 220 in position 4 a circuit is established in series through the winding of relay 222 and the windings of relay 901 of the selected register sender which may be traced from battery through the lower contacts of cam 223, winding of relay 222, the upper left contact of cam 211 (4 to 4½), the lower right contact of cam 127 (2), the left winding of relay 901, the armature and back contact of relay 902, the inner left armature and back contact of relay 903, right contacts of cam 904, the right winding of relay 901, thence to ground at the right contact of cam 905 (1). Relay 222 does not become energized in this circuit due to the inclusion of both windings of relay 901, but relay 901 energizes and establishes a circuit for relay 909 which may be traced from battery through the winding of relay 909, the upper right contact of cam 910 (1), the armature and contact of relay 901 to ground at the lower right contact of cam 911 (1). Relay 909, upon energizing, closes a circuit for advancing sequence switch 920 out of position 1 into position 2 which may be traced from battery, through the magnet winding of switch 920, the lower right contact of cam 912 (1 to 4), the outer right armature and front contact of relay 909, thence to ground at the upper right contact of cam 913 (18 to 2). As soon as the sequence switch leaves position 1, relay 909 deenergizes.

55 In addition, when sequence switch 220 advances into position 4, the subscriber's line became connected over a dialing circuit to the selected register sender. This dialing circuit may be traced from the impulse sender 100, over the tip side of the subscriber's line, tip brushes of the first and second line finders, the outer left armature and front contact of relay 207, the lower contact of cam 212 (4 to 8), the lower left contact of cam 128 (2) to ground through the right winding of impulse relay 600; and the ring conductor of the subscriber's line becomes connected over the ring brushes of the first and second line finders, the inner right armature and front contact of relay 207, the left contact of cam 213 (4 to 8), the lower left contact of cam 129 (2) to battery through the left winding of impulse relay 600. Relay 600 becomes energized over this circuit and at its armature and front contact establishes a circuit for relay 906 which may be traced from battery, through the winding of relay 906, armature and front contact of relay 600, the right contact of cam 907 (1 to 1½), the normal contact and wiper 601 of register A, the interrupter contact of stepping magnet 602 and thence in series over the interrupter contacts of stepping magnets 701, 702, 703, 704, 800, 801, 802 and 803 to ground. Relay 906, upon energizing, establishes a circuit for relay 908, which in turn, prepares a locking circuit for relay 906 for holding this relay energized after sequence switch 920 leaves position 1½, this locking circuit extending from battery, through the winding of relay 906, the armature and front contact of relay 600, the outer left armature and back contact of relay 603.

- to ground at the inner left armature and front contact of relay 908. With the dialing circuit established back to the subscriber's line and sequence switch 920 in position 2, 5 a dialing tone is transmitted to the calling subscriber to apprise him of the fact that the circuits are in condition to receive dialing impulses. This dialing tone is applied from battery through the interrupter 914, 10 the primary winding of induction coil 604, the upper left contact of cam 907 (2 to 3), and thence to ground at the interrupter contact of stepping magnet 803, over the circuit previously traced. The interrupted current 15 flowing in the primary winding of induction coil 604 induces current in the secondary windings of the coil connected in series with the dialing circuit.
- It has been assumed that the subscriber 20 wishes to make a call to the BYEN exchange and first dials the office code BY. In response to the dialing of the letter B the impulse relay 600 becomes deenergized twice. Upon its first deenergization a circuit is 25 established in series through the relays 608 and 607, which may be traced from battery through these relays, the upper contacts of cam 915, the right armature and back contact of relay 606, the armature and back 30 contact of relay 600, the outer left armature and back contact of relay 603, to ground at the inner left armature and front contact of relay 908. Relay 906, which was initially energized over a front contact of 35 relay 600, does not release when its circuit is opened since it is made slow to release and is therefore unaffected by the dial impulses. Relay 607 at its outer armature and front contact closes a circuit extending 40 through the wiper 609 and normal contact of switch RS to battery through the winding of stepping magnet 602 of the A code register. At the same time a holding circuit is established for relays 608 and 607 45 extending through the windings of these relays, the inner armature and front contact of relay 607, the interrupter contact of stepping magnet 602, and thence through the interrupter contacts of the remaining 50 registers to ground at the interrupter contact of magnet 803 for maintaining relays 607 and 608 energized irrespective of the operation of pulsing relay 600. Until the 55 register A has fully completed its first step in response to the first deenergization of relay 600, relay 608 at its armature and front contact establishes a circuit through the stepping magnet 610 of the register steering switch RS, which may be traced 60 from battery, through the magnet winding 610, the right contacts of cam 916, thence to ground at the armature contact of relay 608. Relay 608 being slow to release maintains this circuit until the first series of 65 code impulses ceases. When the first step-

ping impulse is completed, relay 600 energizes, opening the previously traced circuit through relays 607 and 608, and relay 607 upon deenergizing opens the previously traced circuit through stepping magnet 602, 70 which latter magnet releases, permitting the wipers of the register A to advance into contact with the No. 1 terminals of the banks with which they are associated. In a similar manner in response to the second impulse 75 of the first series, the A code register advances into its second position. Following the completion of the first series of impulses, slow releasing relay 608 deenergizes and opens the circuit of stepping magnet 610, 80 advancing the steering switch RS to its No. 1 position.

In response to the transmission of impulses representing the second code letter Y, 85 impulsing relay 600 deenergizes eight times, and since at this time steering switch RS is in position 1, the circuit previously traced from the outer armature of relay 607 now extends over wiper 609, wiper 611 and the No. 2 contact upon which it is resting, to 90 battery through stepping magnet 704 of code register B⁴. In response to this series of impulses, register B⁴ advances to its No. 8 position in the first half of its bank. Following the termination of this series of impulses, the circuit for stepping magnet 610 of the steering relay RS is opened, as previously described, at the armature and front contact of relay 608, and the steering switch advances its wipers to position No. 2. 95

With switch RS in position 2, the circuits of the register sender are in condition to receive the numerical designation of the desired line, which has been assumed to be 5532. The stepping circuits for stepping 100 magnets 800, 801, 802 and 803 are established successively in positions 2, 3, 4 and 5 of the steering switch RS, the numerical registers being set in exactly the same manner as the code registers and the steering switch RS advancing from position to position at the termination of each series of impulses. Following the transmission of the units series of impulses, steering switch RS advances into position 6. At the time the 105 steering switch RS was in position 2 during the reception of the second series of code impulses, a circuit was established for relay 909 extending from battery, through the winding of this relay, the lower right contact of cam 910 (18 to 15), No. 2 terminal upon which wiper 612 is standing, to ground at the lower left contact of cam 913 (17 to 14). Relay 909 upon energizing, 110 with code register B⁴ set in position 8, establishes a circuit for relay 917 which may be traced from battery, through the No. 2 counting relay 923, the armature and back contact of the No. 2' counting relay 924, wiper 705 and the No. 8 terminal, which 115 120 125 130

has been connected by jumper wire at the rack 700, the right winding of relay 917, the inner right armature and contact of relay 909, the upper left contact of cam 910, the lower right contact of this cam, and thence to ground as previously traced over the No. 2 terminal associated with wiper 612 of switch RS. Relay 917 upon energizing locks from ground over its left winding and inner left armature, to battery at the lower contact of cam 918. In addition, relay 909 establishes a circuit for advancing the sequence switch 920 out of position 2 into position 4, which may be traced from battery, through the magnet winding of switch 920, the lower right contact of cam 912 (1 to 4), the outer right armature and front contact of relay 909, thence to ground at the upper right contact of cam 913 (18 to 2). As soon as the sequence switch moves beyond position 3 the initial circuit through relays 917 and 923 is opened and relay 923 deenergizes.

During the movement of sequence switch 920 from position 2 to position 4, a circuit is established for relay 921 since the connection assumed is a full mechanical connection requiring the use of the numerical registers of the sender. The circuit for relay 921 may be traced from battery, through the winding of stepping magnet 704 of register B⁴, wiper 611 of code register A and the No. 2 terminal upon which it is resting, the upper contact of cam 933 (2 to 3), the right contact of this cam, the outer left armature and contact of relay 909, wiper 708 of register B⁴ and the No. 8 terminal upon which it is resting, wiper 804 of the thousands register TH and the normal terminal upon which it is resting, to ground through the winding of relay 921. Relay 921 energizes and locks over its inner left armature to battery at the lower contact of cam 918. Since it is further being assumed that the capacity of the exchange system is not over 200,000 lines, and consequently one switching stage is being suppressed, a circuit is established at this time for relay 935 which may be traced from battery, through the upper right and lower left contacts of cam 934, wiper 707 of register B⁴ and the No. 8 terminal upon which it is resting, thence by jumper connection to rack terminal 706, winding of relay 935, lower contact of cam 936 (2 to 2 $\frac{3}{4}$), upper contact of said cam (2 to 8), thence to ground through the master cam 937 of sequence switch 920 closed while the sequence switch is passing between positions 2 and 3. Relay 935 upon energizing closes an obvious circuit for relay 938, which upon energizing establishes a circuit from ground, over its inner left armature and front contact, through the winding of relay 935, to battery as previously traced until the sequence switch leaves po-

sition 3 $\frac{1}{4}$, and after sequence switch 920 arrives in position 3 $\frac{1}{2}$ to battery through the right contact of cam 918 (3 $\frac{1}{2}$ to 6).

With relay 938 energized when the sequence switch 920 reaches position 4, it does not stop as it would if an extra selection stage were required, but passes through position 4 into position 5. The circuit for sequence switch 920 may be traced from battery, through the sequence switch magnet, the right contacts of cam 919, to ground at the outer right armature and contact of relay 938. Sequence switch 920 remains in position 5 until the thousands register has been set by the thousands digit or until the register steering switch RS advances out of position 2, when relay 909 becomes deenergized and closes a circuit from battery, through the sequence switch magnet, the lower left contact of cam 912 (4 to 14), the outer right armature and back contact of relay 909, thence to ground at the upper right contact of cam 913 (5).

Setting the first group selector.—With sequence switch 920 in position 6 a fundamental circuit is established through the stepping relay 901 of the office sender and control relay 222 of the first group selector 250. This circuit may be traced from battery, through the lower contact of cam 223, winding of relay 222, upper left contact of cam 211 (4 to 4 $\frac{1}{2}$), the lower right contact of cam 127, left winding of relay 901, armature and back contact of relay 902, resistance 939, lower left contact of cam 904 (1 to 6 $\frac{1}{4}$), upper left contact of cam 922 (6), to ground at the outer right armature of relay 938. Relays 901 and 222 both energize in this circuit, relay 901 closing a new circuit for counting relay 923 traced from battery, through the winding of relay 923, thence as previously traced through the inner right armature and front contact of relay 917, the lower left contact of cam 925 (5 $\frac{3}{4}$ to 6), the armature and front contact of relay 901, and the lower right contact of cam 911 to ground. Counting relay 923 upon energizing establishes a locking circuit through its own winding, the winding of the No. 2' counting relay 924, the armature and front contact of relay 923, the outer left armature and back contact of relay 926, thence to ground at the lower contact of cam 905. Relay 924, however, does not energize in this locking circuit since its winding is shunted by ground through the front contact of stepping relay 901.

At the first group selector 250, relay 222 upon energizing establishes a circuit for advancing sequence switch 220 out of position 4 into position 5. This circuit may be traced from battery, through the magnet winding 220, the lower left contact of cam 203 (4), the right armature and front contact of relay 222, thence to ground at the right con-

tact of cam 205 (4 to 17). As soon as sequence switch 220 leaves position $4\frac{1}{2}$ the initial connection of relay 222 to the fundamental circuit is opened at the upper left 5 contact of cam 211 and relay 222 is now maintained energized over the fundamental circuit through the lower right contact of cam 211 ($4\frac{3}{4}$ to 5), left armature and front contact of relay 222, lower contacts of cam 10 256, and thence over the fundamental circuit as previously traced. As soon as sequence switch 220 leaves position 4, relay 234 de-energizes.

With sequence switch 220 in position 5 15 and relay 222 energized, a circuit is established for the trip spindle magnet 248 extending from battery, through the winding of this magnet, the lower contacts of cam 215, the right armature and front contact of relay 222, and thence to ground at the right contact of cam 205, and the trip spindle is started into rotation. During its rotation, the trip spindle shaft interrupter springs 20 251 connect ground over the lower right contact of cam 211, the winding of relay 222, to battery at cam 223 for holding relay 222 energized and shunting down stepping relay 901 of the sender. Upon the first deenergization of stepping relay 901 at the time the 25 30 trip spindle reaches its first brush tripping position, the shunt around the counting relay 924 is opened and this relay energizes in the locking circuit of relay 923. Upon the next energization of stepping relay 901, the 35 40 No. 1 counting relay 927 energizes and locks through the winding of the No. 1' counting relay 928. In response to the second deenergization of relay 901, relay 928 energizes. In response to the next energization 45 50 of relay 901, the No. 0 counting relay 929 energizes and locks in series with relays 902 and 930 and in response to the next deenergization of relay 901 or at the time the trip spindle magnet 248 has positioned the trip spindle in a position to trip the third set 55 60 of brushes, relays 902 and 930 become energized in the locking circuit of relay 929. Relay 902 upon energizing opens the previously traced fundamental circuit, causing the deenergization of control relay 222 of the first group selector and the consequent opening of the circuit of the trip spindle magnet 248.

Upon the energization of relay 930, a circuit is established for advancing sequence switch 920 out of position 6 into position 8, which may be traced from battery, through the magnet winding of switch 920, the lower left contact of cam 912 (4 to 14), the outer right armature and back contact of relay 909, the left armature and back contact of relay 931, to ground at the left armature and front contact of relay 930. Sequence switch 920 is now driven from position 6 and comes 65 to rest in position 8. In leaving position 6, direct locking ground is removed from the energized counting relays and the counting relays are held through resistance 940 and the upper contact of cam 905 through position $6\frac{1}{4}$ when the circuit of the counting 70 relays is opened and they release. Relay 930 also at its right armature and contact establishes a circuit extending from ground, through the lower left contact of cam 131, the lower left and upper right contacts of cam 226, to battery through the winding of relay 262. Relay 262 is later maintained over the left contacts of cam 919, the outer left armature and front contact of relay 908, to ground at the upper left contact of cam 932 when sequence switch 920 leaves position $6\frac{1}{4}$ and opens the locking circuit of relay 930.

At the first group selector, upon the opening of the fundamental circuit, relay 222 deenergizes and opens the circuit of the trip spindle magnet 248 and closes a circuit for advancing sequence switch 220 out of position 5 into position 6. This circuit may be traced from battery, through the magnet winding 220, the lower right contact of cam 206, the right armature and back contact of relay 222, to ground at the right contact of cam 205. As sequence switch 220 approaches position 6, relay 222 again becomes energized over a circuit extending from battery, through the lower contacts of cam 223, the winding of relay 222, the lower contact of cam 201, the armature and back contact of relay 234, to ground at the outer left armature and back contact of relay 224. With sequence switch 220 in position 6 and relay 222 energized, a circuit is established for the brush carriage magnet 241 of the first group selector for rotating the brushes in a trunk hunting movement. This circuit may be traced from battery, through the magnet 241, the upper contact of cam 203 (6), the right armature and front contact of relay 222, to ground at the upper right contact of cam 205. When passing the trip spindle, a set of brushes depending upon the position of the trip spindle is tripped. In the case assumed the trip spindle has taken three steps and consequently the brushes opposite the third level of the group selector bank are tripped. The presence of a free trunk is indicated by the existence of full battery potential on the test terminal of such trunk, and therefore as soon as the test brush 252 encounters such test potential a circuit is established from battery over test terminal 216, brush 252, the right contact of cam 228, the right high resistance winding of relay 234, to ground at the upper contact of cam 217. Relay 234 becomes energized and connects its low resistance left winding in parallel with its right high resistance winding over a circuit extending from test brush 252, the left winding, arma- 100 105 110 115 120 125 130

ture and front contact of relay 234, to ground at the outer left armature of relay 224. The potential on the multiples of test terminal 216 is now altered to such an extent that other group selectors upon testing the test multiples of the selected trunk will find such trunk busy. At its armature and back contact test relay 234 opens the previously traced circuit of relay 222, which in turn opens the circuit of carriage magnet 241 to arrest the hunting movement of the brushes. Relay 222 at its right armature and back contact now establishes a circuit for advancing sequence switch 220 out of position 6 into position 8, which circuit may be traced from battery, through the winding of sequence switch magnet 220, the lower right contact of cam 206, armature and back contact of relay 222, thence to ground at the right contact of cam 205. A circuit is also closed in parallel therewith over the upper right contact of cam 206 to battery through the holding magnet 245, which upon energizing serves to prevent the brushes of the switch from over-running.

To insure that the brushes shall be properly centered upon the terminals of the selected idle trunk a locking circuit is maintained for relay 222 over the upper right contact of relay 201 (6), brush 244 and commutator 269 until the brushes are correctly centered. As soon as sequence switch 220 leaves position $7\frac{1}{2}$, the circuit through the holding magnet 245 is opened and when the sequence switch enters position $7\frac{3}{4}$, relay 222 again energizes over a circuit extending from battery, through the lower contacts of cam 223, winding of relay 222, the upper left contact of cam 201 ($7\frac{3}{4}$ to 10), to ground at the armature and front contact of relay 262.

Setting the distant incoming selector.—With sequence switch 220 of the first group selector 250 in position 8 and sequence switch 920 of the register sender in position 8, a fundamental circuit is extended from the sender to the distant incoming group selector 350. This circuit may be traced from battery, through the winding of control relay 300, the lower contact of cam 301, the ring brush of switch 250, the upper right and lower left contacts of cam 256, the lower right contact of cam 127, the left winding of relay 901, the armature and back contact of relay 902, the inner left armature and back contact of relay 903, the upper contacts of cam 904, the lower right contact of cam 132, the lower left and upper right contacts of cam 255, the tip brush of switch 250, compensating resistance 315, to ground at the right contact of cam 302. Relays 300 and 901 energize in this circuit. At the time sequence switch 920 passed out of position 6, relay 935 deenergized since its circuit was opened at the upper right contact

of cam 918, and consequently relay 938 also deenergized. When sequence switch 920 arrived in position 8, however, relay 935 again energized over a circuit extending from battery, the right contact of cam 918 (8 to 14), the winding of relay 935, the normal contacts associated with the inner left armature of relay 938, the outer right armature and back contact of relay 903, the upper contact of cam 925 (8), the armature and front contact of relay 901, thence to ground at the lower contact of cam 911.

With sender stepping relay 901 energized and the thousands register set into position 5, since it will be recalled that the subscriber dialed the thousands digit 5, a circuit is established for the No. 4 counting relay (not shown) extending from battery, through the winding of this relay, armature and back contact of the corresponding lower counting relay, the No. 4 counting relay lead, the No. 5 terminal and wiper 804 of the thousands register, rack terminal 709, the No. 8 terminal and wiper 708 of the code register B⁴, the upper left and lower right contacts of cam 934, the outer left armature and front contact of relay 917, outer left armature and front contact of relay 938, the outer right armature and back contact of relay 903, the upper contact of cam 925 (8), the armature and front contact of relay 901, thence to ground at the lower contact of cam 911. The upper No. 4 counting relay energizes over this circuit and at its armature and contact locks through the winding of the corresponding lower counting relay and to ground as previously traced through the lower contact of cam 905 (8).

At group selector 350 upon the energization of relay 300, a circuit is established extending from ground, through the right armature and front contact of relay 300, the right contacts of cam 304, the right low resistance winding of relay 305, the left contact of cam 306 (1), the left low resistance winding of relay 307, to battery through the lower contacts of cam 308. Relays 305 and 307 both energize in this circuit. Relay 307 establishes a locking circuit for both of these relays extending from ground at its armature contact, through the contacts of cam 303, thence as previously traced through the windings of relays 305 and 307 to battery at the lower contacts of relay 308, to insure that relay 305 shall be maintained until the sequence switch reaches position 2 regardless of the continued energization of relay 300. Relay 305 upon energizing establishes a circuit which may be traced from ground, through the upper left contact of cam 302, the armature and front contact of relay 305, the right contact of cam 309 (1), to battery through the magnet winding of sequence switch 320 for advancing the sequence switch into position 2. When the se-

quence switch leaves position $1\frac{1}{2}$, the initial connection of relay 300 to the fundamental circuit is opened at the lower contact of cam 301, but relay 300 is maintained connected 5 to the fundamental circuit over the contact of cam 313 (1 to 6), the armature and front contact of relay 300 and the lower contact of cam 310 ($1\frac{3}{4}$ to 2). Upon leaving position 1 relays 305 and 307 become unlocked 10 and deenergize.

With relay 300 energized and sequence switch 320 in position 2, a circuit is established for the trip spindle magnet 348 which may be traced from battery, through 15 this magnet winding, the left contact of cam 311 (2), thence to ground at the right armature and front contact of relay 300. As the trip spindle rotates, the trip spindle cam connects the upper spring of the spring set 20 312 to ground, thereby establishing a holding circuit through the left armature and front contact of relay 300, the contact of cam 313 and the winding of relay 300 in shunt of the winding of the sender stepping 25 relay 901. Consequently, upon each grounding of the spring set 312, as the trip spindle passes through successive brush tripping positions the sender stepping relay 901 deenergizes. In the well known manner, upon 30 each deenergization of stepping relay 901 a lower counting relay of the counting relay group becomes energized until the No. 0' counting relay 930 becomes energized in series with relay 902 when the fundamental 35 circuit is opened at the armature and back contact of relay 902 and the circuit previously traced is established from ground at the left armature and front contact of relay 930 for advancing sequence switch 920 40 out of position 8 into position 10. Upon leaving position $8\frac{1}{4}$ the energized counting relays unlock and deenergize. Since it was assumed that the thousands register was set into its No. 5 position corresponding to the 45 thousands digit 5, the trip spindle was advanced to position 6 for tripping the brushes opposite the sixth level of switch 350.

Upon the opening of the fundamental circuit at the contact of relay 902, the control relay 300 of the group selector deenergizes 50 and opens the circuit of the trip spindle magnet 348 to arrest the movement of the trip spindle and at the back contact of its right armature establishes a circuit over the 55 upper contact of cam 309 (2 to 4) and to battery through the magnet winding 320 for advancing the sequence switch into position 3. With the sequence switch in position 3 a circuit is established for control relay 300 extending from battery, through the winding of this relay, the upper right contact of cam 301 (2 to 4), the armature and back contact of relay 305, the upper and lower left contacts of cam 316, the armature 60 and back contact of relay 317, lower contacts of cam 318, and to ground through the lower springs of set 312, the lower springs of this set being closed so long as the trip spindle is in an off-normal position. Relay 300 upon energizing now establishes a circuit for the 70 brush carriage magnet 341 which extends from battery, through the winding of this magnet, the upper contact of cam 311 (3), to ground at the right armature and front contact of relay 300. The brush carriage is 75 now driven in a trunk hunting movement, the brushes opposite the sixth level of the switch being tripped in passing the trip spindle.

As soon as an idle trunk is found extending to a third group selector, which idle group selector will be assumed to be the selector 450 shown in Fig. 4, battery potential will be encountered by the test brush 352 and test relay 305 becomes energized 80 over a circuit extending from battery, through resistance 442, the lower contact of cam 440 (1 to 7), test brush 352, the lower right contact of cam 306 (3), to ground through the left high resistance winding of 85 relay 305. Relay 305 energizes and connects its low resistance right winding in parallel with its high resistance winding over a circuit extending from brush 352, through the right winding of relay 305, the 90 upper right and lower left contacts of cam 304, the armature and front contact of relay 305, thence as previously traced to ground at springs 312. The connection of the low resistance winding of relay 305 in 95 the circuit of test brush 352 now alters the potential on the multiples of the test terminal of the selected trunk to prevent other selector switches from seizing this trunk. At its armature and back contact relay 305 100 opens the circuit of relay 300, which in turn opens the circuit of carriage magnet 341 and at its right armature and back contact closes a circuit extending over the upper contact of cam 309 for advancing sequence 105 switch 320 out of position 3 and into position 7. A circuit is also closed from ground at the right armature and back contact of relay 300 over the left contacts of cam 309, to battery through the holding magnet 345 110 for insuring that the brush carriage shall not over-run. Until the brushes are properly centered on the terminals of the selected trunk, ground potential is connected from commutator 314, over brush 327, the upper left contact of cam 301 (3), to battery through the winding of relay 300 to maintain the energization of relay 300 until the switch brushes are properly centered. With sequence switch 320 in position 7, the 115 fundamental circuit is extended over the contacts of cams 319 and 321 to the third group selector 450 (Fig. 4).

Setting the third group selector.—With the fundamental circuit so extended and 120

sequence switch 920 of the register sender in position 10, control relay 401 of the third group selector and sender stepping relay 901 become energized for controlling the 5 setting of the group selector 450 under the control of the hundreds register of the sender, which has been set into position 5 in response to the subscriber's dialing the digit 5. The circuit over which relays 401 10 and 901 are energized may be traced as follows: battery, winding of relay 401, lower contact of cam 405 (1 to 1½), ring brush of switch 350, the lower left contact of cam 321 (7 to 8), the left armature and back contact of relay 300, the lower contact of cam 310 (5 to 7), ring brush of switch 250, the upper right and lower left contacts of cam 256, the lower contact of cam 127, left winding of relay 901, armature and back contact of relay 902, inner left armature and back contact of relay 903, upper right contact of cam 904, lower contact of cam 922 (10), the outer right armature and back contact of relay 908 provided that at this 20 time the calling subscriber has completed dialing, the lower right contact of cam 132, the lower left and upper right contacts of cam 255, tip brush of switch 250, compensating resistance 315, lower contacts of cam 319, tip brush of switch 350, to ground at the right contact of cam 402. 25

At the register sender on the energization of relay 901, under the assumption that the hundreds register H has been set into position 5, a circuit is established to the upper No. 5 counting relay, which may be traced in part from battery, through the winding of this counting relay (not shown), over the No. 5 counting relay lead, 30 the No. 4 terminal and wiper 806 of the hundreds register, the lower left contact of cam 941 (10), the outer right armature and front contact of relay 921, the upper contact of cam 911 (10 to 14), the armature and contact of relay 901, to ground through the upper left contact of cam 913 (10 to 14). In the well known manner the energized counting relay locks through the winding of the corresponding lower counting 45 relay (not shown).

At the third group selector 450 upon the energization of relay 401, a circuit is established for relay 410 extending from battery through the right winding of this relay, the upper contact of cam 409, the low resistance left winding of relay 408, the left contacts of cam 407, to ground at the right armature and front contact of relay 401. Relay 410 upon energizing establishes a locking circuit extending through its own winding and the left winding of relay 408 for maintaining relay 408 energized until the sequence switch 420 has left position 1 regardless of the continued energization of 60 relay 401. This locking circuit may be

traced from battery, through the right winding of relay 410, the upper contact of cam 409, the left winding of relay 408, the left contacts of cam 407, contacts of cam 406, the armature and front contact of relay 410, 70 thence to ground through the upper right and lower left contacts of cam 411. Relay 408 upon energizing closes a circuit for advancing sequence switch 420 into position 2, which may be traced from battery, 75 through the magnet winding of the sequence switch, the upper right contact of cam 412, the armature and front contact of relay 408, thence to ground at the lower contact of cam 402. When the sequence switch leaves 80 position 1, relays 408 and 410 unlock and deenergize. As the sequence switch leaves position 1½, the initial connection of relay 401 to the fundamental circuit is opened at the lower contact of cam 405, but this relay 85 is maintained connected to the fundamental circuit over the contact of cam 413 (1 to 6), the left armature and front contact of relay 401, and the lower contact of cam 400 (1¾ to 2). With sequence switch 420 in position 90 2 and relay 401 energized, the circuit of the trip spindle magnet 448 is completed from battery, through the winding of the trip spindle magnet, the lower left contact of cam 414, thence to ground at the right armature and front contact of relay 401.

As the trip spindle rotates, the trip spindle cam intermittently closes the spring contacts 415, whereupon ground is connected intermittently through the upper spring of 100 this set directly to the fundamental circuit, thereby shunting down the stepping relay 901 of the register sender. Relay 401, however, is maintained energized in the local circuit extending over the lower contact of cam 400, to ground at the springs 415. In response to each application of shunting ground by the springs 415, the stepping relay 901 of the sender deenergizes and in the well known manner the counting relays energize in succession, beginning with the No. 5' counting relay, until the No. 0' counting relay 930 energizes in series with relay 902, at which time the trip spindle of the group selector 450 will have rotated into such position as to trip the set of brushes having access to the sixth level of the switch bank. At the register sender upon the energization of relay 902 the fundamental circuit is 105 opened, and upon the energization of relay 930 sequence switch 920 is advanced out of position 10 into position 12, thereby unlocking all energized counting relays and preparing the circuits of the register sender 110 for the next digit selection.

At the group selector 450 upon the opening of the fundamental circuit, relay 401 deenergizes, opening the circuit of the trip spindle magnet 448 to arrest the movement 120 of the trip spindle, and at its right armature and front contact of relay 401.

ture and back contact closes a circuit extending over the lower left contact of cam 412 for advancing sequence switch 420 into position 3. With sequence switch 420 in position 3, a circuit is established for relay 401 which may be traced through the winding of this relay, the right contact of cam 405 (2 to 4), the armature and back contact of relay 408, the upper contacts of cam 475, the armature and back contact of relay 410, thence to ground through the right contacts of cam 411 and the lower springs of the set 415. Relay 401 upon energizing closes a circuit for the brush carriage magnet 441 which may be traced from battery, through the winding of this magnet, the upper contact of cam 414, and to ground at the right armature and front contact of relay 401. The brush carriage is now driven in a trunk hunting movement, the sixth set of brushes being tripped as the carriage passes the trip spindle. As soon as the test brush 452 encounters the test terminal of an idle trunk, which trunk will be assumed to be the trunk terminating in switch 550 (Fig. 5), full battery potential is encountered and test relay 408 becomes energized over a circuit which may be traced from battery, over the upper contacts of cam 522, test brush 452, the lower left contact of cam 409, to ground through the right high resistance winding of relay 408. Relay 408 thereupon energizes and connects its low resistance left winding in parallel with its high resistance winding for the purpose of altering the potential on the test multiples of the selected trunk to prevent other group selectors from selecting this trunk. The circuit over which the left winding is connected may be traced from brush 452, left winding of relay 408, the upper left and lower right contacts of cam 407, the armature and front contact of relay 408, the upper contacts of cam 475, the armature and back contact of relay 410, the right contacts of cam 411, and thence to ground at springs 415. At its armature and back contact relay 408 also opens the circuit of relay 401, which in turn deenergizes and opens the circuit of carriage magnet 441. Relay 401, however, does not deenergize until the brushes are properly centered upon the terminals of the selected trunk since it is held by ground potential applied from commutator segment 423 over brush 422, the upper left contact of cam 405 (3), and thence through the winding of relay 401. As soon as the brushes are properly centered and relay 401 deenergizes, a circuit is established for the holding magnet 445 extending from battery, through the winding of this magnet, the lower contacts of cam 412, and to ground at the right armature and back contact of relay 401. A circuit is also established in parallel therewith through the winding of sequence switch magnet 420 for advancing the sequence switch out of position 3 and into position 7. With the sequence switch in position 7, the fundamental circuit is extended over the lower contacts 70 of cam 403 and the upper contact of cam 404, and over the tip and ring brushes of group selector 450 to the final selector 550.

Setting the final selector.—With the fundamental circuit so extended and the sequence switch 920 of the register sender in position 12, circuits are established for controlling the selector in its tens selection movement in accordance with the setting of the tens register of the sender, it having 80 been assumed that the calling subscriber has dialed the tens digit 3 and that therefore the wipers of the tens register T are standing in position 3. The fundamental circuit over which relays 901 and 500 are now energized may be traced from battery, through the winding of relay 500, the lower left contact of cam 503, the lower right contact of cam 501, thence over the ring brush of selector 450, the upper contact of cam 404 (7 90 to 8), the left armature and back contact of relay 401, the lower contact of cam 400 (5 to 7), ring brush of selector 350, the lower left contact of cam 321 (7 to 8), the left armature and back contact of relay 300, 95 the lower contact of cam 310, thence as previously traced through the winding of sender stepping relay 901, returning over the tip conductor of the fundamental circuit lower contacts of cam 403, tip brush of 100 selector 450, to ground at the right contact of cam 504 (1 to 4). At the register sender, relay 901 upon energizing closes a circuit for the No. 3 counting relay, which may be traced in part from battery, through the 105 winding of the No. 3 counting relay (not shown), the No. 3 counting relay lead, the No. 3 terminal on which the wiper 807 of the tens register T is resting, the lower right contact of cam 941, thence as previously traced through the contact of stepping relay 901, to ground at the upper left contact of cam 913. This counting relay locks in the well known manner through the corresponding No. 3' counting relay. 110

At the final selector switch upon the energization of relay 500 in the fundamental circuit, a circuit is established for relay 505 which may be traced from battery, through the left contact of cam 506, winding of relay 505, the contacts of cam 507, the right armature and front contact of relay 500, thence to ground through the left contact of cam 508. Relay 505 upon energizing locks directly to ground through its 115 armature and front contact and establishes a circuit for relay 512, which may be traced from battery, through the winding of relay 512, the lower contacts of cam 511, the lower left contact of cam 510, the contacts 120

125

130

- of cam 507, and thence to ground at the contact of relay 505. Relay 512 closes a circuit over the lower right contact of cam 513 for driving switch 520 into position 2.
- 5 As soon as the sequence switch leaves position 1, relay 512 deenergizes since its circuit is then open at cam 511.
- With sequence switch 520 in position 2 a circuit is closed for the trip spindle magnet 548 extending from battery through the magnet, the lower right contact of cam 510, the right front contact of relay 500 to ground at the left contact of cam 508. As the trip spindle magnet 548 causes the rotation of the trip spindle, the springs 514 are intermittently closed and a circuit is established from battery, through the winding of relay 500, the upper contact of cam 503 (2 to 6), and to ground at springs 514. This circuit, while maintaining relay 500 energized, shunts the stepping relay of the sender. At the sender in response to each deenergization of stepping relay 901, a lower counting relay of the counting relay set becomes energized until when the trip spindle of the final selector has advanced to a position for tripping the fourth set of brushes, the No. 0' counting relay 930 energizes in series with relay 902. When the relay 902 energizes the fundamental circuit is opened, and when relay 930 energizes the sequence switch 920 is advanced out of position 12 into position 14, in the manner previously described.
- 35 At the final selector, upon the opening of the fundamental circuit, relay 500 deenergizes and at its right armature and back contact establishes a circuit for advancing sequence switch 520 into position 3. This circuit may be traced from battery, through the magnet winding of switch 520, the left contact of cam 515 (2), the right armature and back contact of relay 500, thence to ground at the left contact of cam 508. During the passage of the sequence switch through position 2 3/4, a circuit is established for relay 512 which may be traced from battery, through the winding of this relay, the lower right contact of cam 515 (2 3/4 to 3), the right armature and back contact of relay 500, the right contact of cam 516 (2 to 3), and thence to ground at the lower springs of the set 514, which lower springs are closed so long as the trip spindle is in an off-normal position.
- With sequence switch 520 in position 3 and sequence switch 920 of the register sender in position 14, units selection at the final selector 550 takes place. Relay 500 and sender stepping relay 901 now become energized over the fundamental circuit previously traced, relay 500 upon energizing locking itself to the fundamental circuit over the upper contact of cam 509, the left armature and front contact of relay 500, and the upper right contact of cam 502, and opens the circuit of relay 512. Relay 512 after an interval deenergizes, and at the back contact of its armature closes a circuit extending over the upper right contact of cam 513 for advancing sequence switch 520 into position 4.
- At the register sender with relay 901 energized and the sequence switch 920 in position 14, a circuit is established for relay 942 which may be traced from battery, through the winding and normally closed left armature contacts of this relay, the upper contact of cam 941 (14), the outer right armature and front contact of relay 921, the upper contact of relay 911, the armature and front contact of stepping relay 901, thence to ground at the upper left contact of cam 913. Since the hundreds digit was 5 and therefore odd, a circuit is effective for the No. 10 counting relay 943, which may be traced from battery through the winding of this relay, the armature and back contact of the lower No. 10' counting relay 944, the right armature and back contact of relay 926, the No. 5 terminal and wiper 810 of the hundreds register H, the outer left armature and front contact of relay 942, and thence as traced to ground at the upper left contact of cam 913. A circuit is also closed for relay 931 which may be traced from ground, through the left armature and back contact of the No. 0' counting relay 930, the inner left armature and back contact of relay 926, the winding of relay 931, the off-normal contacts and wiper 808 of the units register, the No. 5 terminal and wiper 805 of the hundreds register, thence to battery through the lower contacts of cam 915.
- At the final selector, with sequence switch 520 in position 4 and control relay 500 energized over the fundamental circuit in series with relay 901, a circuit is established for the carriage magnet 541, which may be traced from battery, through the winding of this magnet, the upper left contact of cam 517, the right armature and front contact of relay 500, thence to ground at the left contact of cam 508. As the brush carriage progresses from position to position, the springs 557 are intermittently closed, connecting ground over the upper contact of cam 503 for maintaining the relay 500 energized and for shunting down the sender stepping relay 901. Since the No. 10 counting relay was energized, the counting relays all become energized in succession until the No. 0' counting relay 930 energizes in series with relay 902. At this time the brush carriage of the final selector will have advanced over the first ten sets of terminals in the switch bank and the fourth set of brushes will have been tripped. With relay 930 energized, the shunt previously existing around the winding of relay 926 is removed.

- and this relay energizes in the circuit of relay 931, closing a shunt around the winding of relay 931 to cause its deenergization, and at the back contact of its outer left armature opening the locking circuits of all the energized counting relays. Since relay 931 is energized at the time relay 930 energizes the circuit extending from the ground at the left armature of relay 930 is not effective to advance sequence switch 920 out of position 14. Relay 926 at its right armature also opens the circuit over which the No. 10 counting relay 943 was previously energized to prevent the reenergization of this relay, and at the front contact of its armature establishes a circuit for energizing the No. 1 counting relay, it having been assumed that the units register was set into position 2 for the digit 2. The circuit of the No. 1 counting relay 927 may be traced from battery, through the winding of this relay, the armature and back contact of relay 928, the No. 2 terminal and wiper 809 of the units register, the right armature and front contact of relay 926, the No. 5 terminal and wiper 810 of the hundreds register, and thence as previously traced to ground at the upper left contact of cam 913. At this time the fundamental circuit previously traced is again established, and the movement of the brush carriage of the final selector continues until two additional pulses have been transmitted from the brush set 557 for shunting down the sender stepping relay 901, when the No. 0' counting relay 930 again energizes in series with relay 902. Upon the energization of relay 930 a circuit is established from ground, through the left armature and front contact of this relay, the left armature and back contact of relay 931, the outer right armature and back contact of relay 909, the lower left contact of cam 912, and through the magnet of sequence switch 920 for advancing the sequence switch out of position 14 and into position 15. As soon as sequence switch 920 leaves position 14, the locking circuits previously traced for relays 926, 917, 921, 935 and 938 are opened and these relays release. Relay 942 which was locked over its inner left armature and front contact, and the upper right contact of cam 905 is also unlocked and releases.
- The final selector has now advanced its tripped set of brushes thirteen steps. It was necessary to advance the set an extra ten steps since the capacity of the switch is 200 lines, in the case assumed having access to lines 400 to 599 inclusive, in the five thousands group. In the well known manner the switch bank is divided vertically into two halves, the first half of the bank having lines in the even or four hundreds group terminating therein, and the second half having lines in the odd or five hundreds group terminating therein. Had the hundreds digit been even and therefore terminating in the first half of the bank, relays 931 and 926 would not have been operated since the hundreds register would have been standing upon an even numbered terminal and therefore the extra ten impulses would not have been counted.
- At the final selector upon the opening of the fundamental circuit, relay 500 deenergizes, opening the circuit of the brush carriage magnet 541. Relay 500, however, does not release until the tripped set of brushes is properly centered upon the terminals of the desired line since it is maintained over the upper contact of cam 503, the brush 557 and the grounded segment 552 until the brushes are correctly centered. Upon the deenergization of relay 500 a circuit is established for the holding magnet 545 to insure the stopping of the brush carriage, which circuit may be traced from battery, through the winding of this magnet, the lower left contact of cam 513, the left contact of cam 515, the right armature and back contact of relay 500, thence to ground at the left contact of cam 508. A circuit is also closed in parallel therewith through the magnet winding of sequence switch 520 for advancing the switch out of position 4 into position 7. As the sequence switch advances out of position 5, a circuit is established for relay 512 which extends through the lower contacts of cam 511, the armature and back contact of relay 519, the left contacts of cam 521, and to ground over the sleeve brush 452 of selector 450 through the winding of test relay 408.
- Restoration of register sender.*—All selections have now been completed, and it being no longer necessary to hold the register sender in connection with the established connection, the register sender proceeds to release and disassociate itself from the connection. With sequence switch 920 in position 15, a circuit is established for relay 608, which may be traced from battery, through the winding of this relay, the left contact of cam 946, wiper 612 of the steering switch RS, the No. 6 terminal upon which it is resting, the off-normal contacts and wiper 812 of the units register, to ground at the interrupter contact of units register stepping magnet 803. A circuit is also established through the winding of the units register stepping magnet 803 extending from battery, through the winding of this magnet, the No. 6 terminal and wiper 609 of the register steering switch RS, the lower contacts of cam 946, and thence to ground as previously traced at the interrupter contact of magnet 803. Magnet 803 energizes and through the interruption of its own circuit advances the wipers of the register to normal, when the circuit previously traced

for relay 608 is opened at the wiper 812 of the register. It will be noted that the register has two normal positions and upon restoring will be arrested in the normal position first reached. Relay 608 upon deenergizing closes a circuit extending from ground, through its armature and back contact, the left contacts of cam 945, the interrupter and contact of stepping magnet 610 of the steering switch, the lower left contact of cam 933 (15), wiper 616 and the No. 6 terminal upon which it is resting, to battery through the winding of relay 606. Relay 606 upon energizing closes a circuit extending from ground, through its left armature and contact, the upper contact of cam 947, to battery through the winding of relay 909. With relay 909 energized, a circuit is established through the magnet winding 610 of the register steering switch, extending through the inner left armature and contact of relay 909, through the upper right and lower left contacts of cam 945, to ground at the armature and back contact of relay 608. Magnet 610 upon energizing in this circuit opens the previously traced circuit for relay 606, which in turn opens the circuit of relay 909 and thereby the circuit of magnet 610. Magnet 610 upon deenergizing advances the wipers of the register steering switch into contact with the seventh set of terminals.

The circuit of relay 608 is now again established over wiper 612, the terminal upon which it is resting, the restoring bank and wiper 813 of the tens register, and the interrupter contacts of stepping magnets 802 and 803 to ground. The stepping magnet 802 of the tens register is now energized in the same manner as previously described in connection with the stepping magnet 803 of the units register, and the tens register is restored to normal. In a similar manner, with the register steering switch RS in successive positions, the hundreds, thousands, B and A registers are restored to normal position. When the register A reaches its normal position, a circuit is established for relay 942 extending from battery, through the winding of this relay, the lower left contact of cam 907, the normal contact and wiper 601 of register A, thence to ground over the stepping magnet interrupter contacts of all of the registers, to ground at the interrupter contact of magnet 803. Relay 942 upon energizing closes a circuit for advancing sequence switch 920 into position 18, which may be traced from battery, through the winding of the sequence switch magnet, the outer right armature and front contact of relay 942, thence to ground at the right armature and back contact of relay 906. When the sequence switch leaves position 15 relay 942 deenergizes, and when the sequence switch reaches position 18 a circuit is established through the magnet winding of the sequence switch, over the upper left contact of cam 912 (12 to 18), the outer left armature and back contact of relay 921, to ground at the upper right contact of relay 913 for advancing the sequence switch into normal position. The register sender has now been completely restored to normal and may be taken for use in controlling the establishment of another connection.

As soon as the sequence switch 920 advanced out of position 14 following the completion of units selection control, the circuit previously traced extending over the lower contacts of cam 919 and the lower left contact of cam 131 through the winding of relay 262 at the first group selector is opened and relay 262 deenergized, opening the circuit of relay 222. With relay 222 deenergized, sequence switch 220 advances out of position 8 into position 10 by reason of a circuit extending through the magnet winding of the sequence switch, over the lower right contact of cam 206 (5 to 8), the right armature and back contact of relay 222, to ground at the right contact of cam 205. The sequence switch now remains in position 10 awaiting the connection of the bridge across the inter-office trunk at the distant incoming selector 350. With sequence switch 220 in position 10, the pulsing leads extending to the sender are disconnected at cams 212 and 213, and the calling line is cut through to the windings of relay 237 and coil 231.

At the final selector, with sequence switch 520 in position 6, a test is made to determine if the selected line is idle. It will first be assumed that the line is found to be idle and that the test relay 505 becomes energized over a circuit extending from battery, test terminal of the selected line, brush 552, the right contacts of cam 506, the winding of relay 505, to ground at the right contact of cam 508. Relay 505 upon energizing locks over its armature and front contact, shunting out the resistance 533 to alter the potential upon the test terminal of the called line, marking it busy to all other final selectors having access thereto.

When the sequence switch 520 of the final selector advanced out of position 4 into position 7 following the completion of units selection, battery potential was removed from the sleeve conductor at the upper contacts of cam 522 during the passage of the sequence switch between the positions 4 and 5, permitting the deenergization of the test relay 408 of the group selector 450. Relay 408 upon deenergizing establishes a circuit for relay 401, which may be traced from battery, through the winding of relay 401, the right contact of cam 405, the armature and back contact of relay 408, to ground at the lower contact of cam 402. Relay 401 upon energizing establishes a circuit for

advancing sequence switch 420 out of position 7 into position 9, this circuit extending from battery, through the winding of sequence switch magnet 420, the right contact 5 of cam 414 (7 to 10), to ground at the armature and front contact of relay 401. As soon as sequence switch 420 leaves position 8, the circuit of relay 401 is opened at the right contact of cam 405. When the sequence switch reaches position 9, relay 408 10 reenergizes over the upper left and lower right contacts of cam 416, and at its armature and front contact establishes a circuit for continuing the advance of sequence switch 420 out of position 9 into position 10, this circuit extending from battery, through the winding of sequence switch magnet 420, the upper right contact of cam 412, the armature and front contact of relay 408, 15 to ground at the lower contact of cam 402. In position 10 relay 408 again energizes, establishing the same circuit for advancing sequence switch 420, out of position 10 into the talking position 11. With sequence switch 420 in position 11 relay 408 deenergizes and the tip and ring brushes of selector switch 450 are connected over contacts of cams 403 and 404 directly to the tip and ring conductors of the trunk circuit. The sleeve brush 452 of the selector switch is now connected directly to ground at the right contact of cam 409. 20

As soon as sequence switch 420 advances out of position 7, the circuit previously traced for the test relay 305 of the selector switch 350 is opened at the lower contact of cam 440 and relay 305 deenergizes, closing a circuit for relay 300 which may be traced from battery, through the winding of relay 300, the right contact of cam 301 (7 to 8), the armature and back contact of relay 305, 35 to ground at the left contact of cam 302. Relay 300 upon energizing establishes a circuit from ground at its right armature and front contact, through the lower right contact of cam 311 for advancing sequence switch 320 out of position 7. As soon as sequence switch 320 leaves position 8, relay 300 deenergizes, arresting the sequence switch in 40 position 9. With the sequence switch in position 9, a circuit is established for relay 305 extending from ground, through the left winding of relay 305, the upper right and lower left contacts of cam 321, through the interrupter 322, to battery. With relay 305 energized, a circuit is established through the magnet winding of sequence switch 320, the right contact of cam 309 (9 to 10), the armature and front contact of relay 305, 45 to ground at the upper left contact of cam 302, advancing the sequence switch into position 10. Upon leaving position 9, relay 305 deenergizes, but again energizes in position 10 as soon as the interrupter 323 reaches a circuit closing position, the circuit for 50 relay 305 now extending through the right contacts of cam 321. Relay 305 upon reenergizing again establishes the previously traced circuit for advancing sequence switch 320 out of position 10 into the talking position 11. With the sequence switch 320 in position 11, relay 305 becomes deenergized, ground potential is applied to the test brush 352 over the upper contact of cam 306, and the tip and ring brushes of the switch are 55 connected to ground and battery, respectively, over circuits hereinafter traced. 70

At the final selector as soon as sequence switch 520 reaches position 7, relay 519 becomes bridged across the tip and ring conductors of the trunk circuit extending back to the group selector 450 and is energized over a circuit which may be traced from battery, through the winding of relay 317 at the incoming group selector 350, the lower 80 right contact of cam 321 (11 to 14), ring brush of switch 350, the lower contact of cam 404 (8 to 14), ring brush of selector 450, the lower left contact of cam 501, the lower contact of cam 502 (7 to 7½), winding 85 of relay 519, the lower left contact of cam 504 (7 to 7½), tip brush of selector 450, the lower right and upper left contacts of cam 403, tip brush of selector 350, the right contacts of cam 319, winding of coil 325, upper 90 left and lower right contacts of cam 304 (11 to 14), to ground at the right armature and front contact of relay 300. Relay 300 is energized at this time over a circuit which 100 may be traced from battery, through the winding of this relay, the lower contact of cam 326, and to ground at the armature and front contact of relay 307, relay 307 being at the time energized over a circuit extending from battery, through the winding of relay 262, the outer right armature and front contact of relay 207, the upper contacts of cam 256, ring brush of selector 250, upper 105 left contact of cam 310, impedance coil 324, windings of relay 307, upper contacts of cam 308, tip brush of selector 250, upper contacts of cam 255, coil 257, to ground at the armature and front contact of relay 237. It will be recalled that relay 237 was energized over 110 the calling subscriber's line as soon as dialing was completed and the sequence switch 220 of the first group selector advanced out of position 8. Relays 519 and 317 energize in this circuit. Relay 519 upon energizing 115 opens at its armature and contact the circuit previously traced for relay 512, which in turn deenergizes, closing a circuit extending from ground, through its armature and back contact, over the upper right contact of cam 513 for advancing sequence switch 520 out of position 7 into position 9. As soon as the sequence switch leaves position 7½, relay 519 deenergizes, and when the sequence switch reaches position 8, relay 512 again energizes 120 over a circuit extending from battery, 125 130

through its winding, the lower right and upper left contact of cam 522, sleeve brush 452 of selector 450, to ground at the right contact of cam 409. When sequence switch 520 reaches position 9, it is advanced into position 11 over a circuit extending through its magnet winding, the upper left contact of cam 513, the armature and back contact of relay 519, the upper left and lower right contacts of cam 521, to ground at the armature and front contact of relay 512. In passing through position 10, a circuit is established for relay 500 extending through the winding of relay 500, the right contacts of cam 521, to ground at the armature and front contact of relay 512. With relay 500 energized, when the sequence switch 520 reaches position 11, it is advanced into position 12 over a circuit extending from battery, through the winding of the sequence switch, the upper left contact of cam 513, the lower left contact of cam 510, the right armature and front contact of relay 500, to ground at the left contact of cam 508. Relay 500 is maintained energized after sequence switch 520 leaves position 11½ over a circuit extending through its winding, the upper contacts of cam 521, the armature and back contact of relay 519, the lower left contact of cam 510, the right armature and front contact of relay 500, to ground at the left contact of cam 508. As the sequence switch leaves position 11¼, relay 512 becomes deenergized, but again energizes in position 12 over a circuit extending from battery, through its winding and the lower contacts of cam 522 as soon as the interrupter 523 reaches a circuit closing position. With the sequence switch in position 12 and relay 512 energized, a circuit is established over the lower right contact of cam 513 and the armature and front contact of relay 512 for advancing the sequence switch into position 13. When the sequence switch leaves position 12, relay 512 deenergizes but is reenergized in position 13 over the left contacts of cam 511 and the interrupter 524 as soon as this interrupter reaches a circuit closing position.

Ringing up the calling subscriber.—With the sequence switch 520 in position 13, ringing current is applied to the called line from the source 525 through the right contact of cam 526, winding of relay 519, upper right contact of cam 509, left armature and front contact of relay 500, upper contacts of cam 502, ring brush of selector 550, over the subscriber's line loop, tip brush of selector 550, to ground through the right contacts of cam 527. After a time interval, as determined by the operation of interrupter 524 and the reenergization of relay 512, sequence switch 520 is advanced out of position 13 over a circuit extending through the lower right contact of cam 513 and the armature

and front contact of relay 512, and upon reaching position 14 applies ringing current from the source 529 through the interrupter 530 and the lower left contact of cam 526, thence over the circuit previously traced, 70 for intermittently ringing the call bell of the called line. When the called subscriber answers, marginal relay 519 energizes, unlocking relay 500, which cuts off the ringing current and advances sequence switch 75 520 out of the ringing position 14 into the talking position 15. The circuit over which switch 520 is advanced may be traced from battery, through the magnet winding of switch 520, the left contact of cam 515, the 80 right armature and back contact of relay 500, to ground at the left contact of cam 508. With sequence switch 520 in the talking position 15, relay 512 is maintained energized over a circuit extending from battery, 85 through its winding, the lower right and upper left contacts of cam 522, brush 452 of selector 450, to ground at the right contact of cam 409, and is thus maintained energized until the release of the connection by the 90 calling subscriber.

At the time relay 317 energized in series with relay 510 prior to the ringing of the called subscriber, relay 317 established a short circuit around the right high resistance 95 right winding of relay 307, which may be traced from one terminal of this winding, through the armature and front contact of relay 317, the left contacts of cam 318 to the other terminal of the high resistance winding of relay 307. The current now flowing in the circuit extending back to the first group selector is increased to such an extent that relay 262 becomes energized. Relay 262 upon energizing closes a circuit extending from ground, through its armature and front contact, the left contact of cam 201 (7¾ to 10), winding of relay 222, to battery through the lower contacts of cam 223, whereupon relay 222 energizes. With relay 222 100 energized, a circuit is established from battery, through the winding of sequence switch magnet 220, the lower left contact of cam 203 (10), the right armature and front contact of relay 222, to ground at the right contact of cam 205 for advancing sequence switch 220 out of position 10 into position 11. In leaving position 10 the circuit of relay 222 is opened at the left contact of cam 201 since if the called line was idle the 110 circuit of relay 262 is maintained only while sequence switch 520 is passing from position 7 to 7½ and no locking circuit for relay 222 is effective. Relay 222 at its right armature and back contact closes a circuit 115 for advancing sequence switch 220 out of position 11 into position 12. This circuit may be traced from battery, through the magnet winding of sequence switch 220, the lower right contact of cam 206, the right 120

125 130

armature and back contact of relay 222, thence to ground at the right contact of cam 205. If at the time sequence switch 222 reaches position 11 the connection has 5 become connected through to the called line and the called subscriber has responded, relay 262 will again be energized through the energization of relay 317. At this time relay 317 will be energized over the called 10 subscriber's line loop in a circuit which may be traced as previously from the winding of relay 317, over the ring brushes of selectors 350 and 450, the upper contact of cam 501, ring brush of selector 550, over the subscriber's line loop, tip brush of selector 550, lower right and upper left contacts of cam 527, thence as previously traced to ground at the right armature and front contact of relay 300. With relay 262 energized at this 15 time, a circuit is completed for relay 222 extending from battery, through the lower contacts of cam 223, winding of relay 222, upper left contact of cam 201 (12) to ground at the armature and front contact of relay 262. With relay 222 energized, a circuit is 20 established over the lower left contact of cam 203, the right armature and front contact of relay 222, and the right contact of cam 205 for advancing sequence switch 220 into the talking position 13. A talking circuit 25 is now established over the heavy conductors indicated in Figs. 1, 2, 3, 4 and 5, the calling subscriber being supplied with talking battery through the winding of relay 237 and the winding of coil 231, and the called 30 subscriber being supplied with talking current through the winding of relay 317 and the winding of coil 325.

Had the called line been busy at the time 40 sequence switch 520 of the final selector advanced to position 6, relay 505 would not have energized, and therefore when the sequence switch 520 reached position 7 a circuit would have been established for relay 500 extending through the lower contacts of cam 518, to ground at the armature and back contact of relay 505. When, therefore, sequence switch 520 advanced out of position 7½, relay 519 would have remained energized over a circuit extending from battery, through the upper contact of cam 526, the winding of relay 519, the upper left and lower right contacts of cam 518, to ground at the armature and back contact of relay 505. When, therefore, sequence switch 520 arrived in position 9, with relay 519 energized, no circuit is established for advancing the sequence switch out of position 9. With the sequence switch in position 9, the windings of tone coil 531 are connected over the armatures and front contacts of relay 500 to the tip and ring conductors of the trunk circuit for sending back a busy tone signal to the calling subscriber. Under these conditions when sequence switch 520 reaches position 7¾, relay 317 is maintained energized over the circuit previously traced to cam 502 thence over the upper right contact of this cam (7 to 9), left armature and front contact of relay 500 to ground at the lower contact of cam 509 (7¾ to 9). With relay 317 maintained energized, relay 262 at the first group selector locks relay 222 energized in position 11 of sequence switch 220 as hereinafter described.

Restoration of a connection.—Under the assumption that the call was successfully established, when the calling subscriber restores his receiver to the switchhook upon the termination of the conversation, the circuit of relay 237 is opened, in turn opening the circuit previously traced through the windings of relays 262 and 307. Upon the deenergization of relay 237, a circuit is closed from ground through the armature and back contact of this relay, the lower contact of cam 200, the left contacts of cam 218 (13), the winding of relay 222 to battery through the lower contacts of cam 223. Relay 222 energizes in this circuit and at its right armature and front contact establishes a circuit for advancing sequence switch 220 out of the talking position 13 and into position 17. The circuit for the sequence switch may be traced from battery through the magnet winding of the sequence switch, lower left contact of cam 203, right armature and front contact of relay 222 to ground at the right contact of cam 205. As soon as the sequence switch leaves position 13½, the locking circuit of relay 207 is opened at the lower contact of cam 210 and relay 207 deenergizes. With relay 207 deenergized, a new circuit is established from battery through the windings of cut-off relay 107, and message register magnet 108 in parallel, thence as previously traced through the winding of relay 235, the normal contacts associated with the inner left armature of relay 207, the outer right armature and back contact of relay 224 to reversed battery through the left contacts of cam 232. The current now flowing through the message register magnet is of sufficient strength to operate it.

During the passage of the sequence switch through position 14, a circuit is established for the trip spindle magnet 248 extending through the right contacts of cam 215 to ground through the lower springs of spring set 251. As soon as the trip spindle magnet has restored the trip spindle to normal position, the lower-most spring of the set 251 enters the normal deep notch of the trip spindle cam and the circuit of the magnet is opened. When the sequence switch 220 left position 13, the circuit of relay 234 was opened and therefore, when the sequence switch reaches position 16¾, a circuit is established for relay 222 which may be traced from battery through the lower contacts of

cam 223, winding of relay 222, the lower contact of cam 201, the armature and back contact of relay 234 thence to ground at the outer left armature and back contact 5 of relay 224. With relay 222 energized, a circuit is established for the brush carriage magnet 241 as soon as the sequence switch reaches position 17 which may be traced through the magnet 241, upper contact of 10 cam 203, armature and front contact of relay 222, to ground at the right contact of cam 205. When the brush carriage reaches its normal position, relay 234 energizes over a circuit extending from the 15 normal segment of the brush carriage commutator, brush 244, lower contact of cam 228, right winding of relay 234 to ground at the contact of cam 217. Relay 234 upon energizing, opens the circuit of relay 222 which deenergizes and closes a circuit for 20 advancing sequence switch 220 into position 18. This circuit extends from battery through the sequence switch magnet 220, the lower right contact of cam 206, the 25 right armature and back contact of relay 222 to ground at the right contact of cam 205. A circuit is also closed in parallel therewith over the upper right contact of cam 206 for the holding magnet 245 for arresting 30 the movement of the brush carriage. As soon as the sequence switch leaves position 17½, relay 234 deenergizes and with sequence switch 220 in position 18, closes a 35 circuit for relay 224 which may be traced from battery through the lower left and upper right contacts of cam 223, winding of relay 224, upper contact of cam 200 to ground at the armature and back contact of relay 237. Relay 224 upon energizing, 40 closes a circuit extending from battery through sequence switch magnet 220, the lower right contact of cam 206, right armature and back contact of relay 222, outer left armature and front contact of relay 224 to ground for advancing the sequence switch 45 into normal position 1. In position 1, the circuit of relay 224 is opened. The circuits of the first group selector 250 are now in normal position. The circuit previously traced for relays 235, 107 and magnet 50 108 is now open and cut-off relay 107 reconnects the line relay 101 to the calling line. At the second group selector 350, upon the opening of the circuit of relay 307, the holding circuit of relay 300 is opened and sequence switch 320 is advanced out of position 11 into position 16. The circuit for sequence switch 320 extends from battery through the magnet winding of the sequence 55 switch, upper contact of cam 309 to ground at the right armature and back contact of relay 300. In passing through position 15½, relay 300 again energizes over a circuit extending through the upper right contact of cam 301, the armature and back contact 60 of relay 305, upper right and lower left contacts of cam 316, armature and back contact of relay 317, lower contacts of cam 318, to ground at springs 312. In position 16, a circuit is established for trip spindle 70 magnet 348 extending through the left contact of cam 311 to ground at the right armature and front contact of relay 300. When the trip spindle reaches normal position, ground is removed at springs 312 and 75 relay 300 deenergizes closing at its right armature and back contact and over the upper contact of cam 309, a circuit for advancing sequence switch 320 into position 18. In position 18, relay 300 again energizes over the circuit previously traced through cams 301 and 302 and establishes a circuit for the brush carriage magnet 341. This circuit may be traced from battery 80 through the magnet 341, the upper contact of cam 311, to ground at the right armature and front contact of relay 300. When the brush carriage reaches normal position, a circuit is established from battery through the normal brush-carriage commutator segment, brush 327, the upper contacts of cam 321 to ground through the left winding of relay 305. Relay 305 upon energizing, opens the circuit of relay 300 which upon deenergizing, closes a circuit 90 extending over the upper contact of cam 309 for advancing sequence switch 320 into normal position. The circuits of the second group selector 350 are now in normal condition. 100

As soon as sequence switch 320 of the second group selector leaves position 14, cam 306 opens its upper contact thereby opening the holding circuit of relay 410. Relay 410 upon deenergizing, establishes a circuit 105 for relay 401 extending through the winding of this latter relay, the contact of cam 421, the armature and back contact of relay 410, to ground through the upper right and lower left contacts of cam 411. Relay 401 upon energizing, closes a circuit extending through its right armature and front contact over the upper left contact of cam 412, for advancing sequence switch 420 into position 110 115. As soon as sequence switch 420 leaves position 14, relay 401 deenergizes but again energizes when the sequence switch reaches position 16 over a circuit extending through the right contact of cam 405, the armature and back contact of relay 408, the upper contacts of cam 475, armature and back contact of relay 410, the right contacts of cam 411 to ground at the springs 415. With sequence switch 420 in position 16 and relay 401 energized, a circuit is established for 120 the trip spindle magnet 448 extending from battery through the winding of this magnet, the lower left contact of cam 414, to ground at the right armature and front contact of relay 401. As soon as the trip spindle 125 130

reaches normal position springs 415 open and relay 401 deenergizes closing at its right armature and back contact a circuit extending over the lower left contact of cam 412 for advancing sequence switch 420 into position 18. As soon as the sequence switch reaches position 18, relay 401 again energizes and closes a circuit for brush carriage magnet 441, extending from this magnet over the upper left contact of cam 414 to ground at the right armature of relay 401. As soon as the brush carriage reaches normal position, the brush 422 engages the normal segment of the brush-carriage commutator and completes a circuit extending through the upper contacts of cam 416 to ground through the right winding of relay 408. Relay 408 energizes in this circuit opening the circuit of relay 401 which energizes and opens the circuit of the carriage magnet 441. Relay 401 at its right armature and back contact establishes a circuit extending in parallel over the lower left contact of cam 412, through the sequence switch magnet 420 and through the lower right contact of cam 412 through the holding magnet 445. The magnet 445 arrests the movement of the brush carriage and sequence switch magnet 420 advances the sequence switch cams into normal position. The circuits of the third group selector 450 are now in normal condition.

When sequence switch 420 leaves position 14, cam 409 opens the circuit extending over the sleeve brush 452, the upper left and lower right contacts of cam 522, through the winding of relay 512 at the final selector and relay 512 deenergizes closing at its armature and back contact a circuit for advancing sequence switch 520 out of position 15 into position 16. If the called subscriber has not at this time restored his receiver to its switchhook, relay 512 is again energized over the called subscriber's line loop in a circuit extending from battery through the winding of relay 512, the lower left and upper right contacts of cam 511, the left armature and back contact of relay 500, the upper contacts of cam 502 thence over the subscriber's line loop, the lower contacts of cam 527, the right armature and back contact of relay 500 to ground at the upper contact of cam 515 and sequence switch 520 upon reaching position 16 is arrested. When the called subscriber restores his receiver to the switchhook, relay 512 deenergizes and at its armature and back contact completes a circuit extending over the upper right contact of cam 513, for advancing the sequence switch out of position 16 into position 17. In position 17, a circuit is established for relay 500 extending through the winding of this relay, the left contact of cam 516 to ground at the trip spindle off-normal contacts 514. With relay 500 energized, a circuit is established for the trip spindle magnet 548 extending through the winding of this magnet, the right contact of cam 510, right armature and front contact of relay 500 to ground at the left contact of cam 508. With the trip spindle in normal position, the springs 514 open permitting relay 500 to deenergize. Relay 500 upon deenergizing, opens the circuit of the trip spindle magnet 548 and establishes a circuit for advancing sequence switch 520 into position 18. This circuit may be traced from battery through the winding of magnet 520, left contact of cam 515, right armature and back contact of relay 500 to ground at the left contact of cam 508. With sequence switch 520 in position 18, a circuit is established for the brush carriage magnet 541 extending through the winding of this magnet, right contact of cam 517, right armature and back contact of relay 500 to ground at the left contact of cam 508. When the brush carriage reaches normal position, a circuit is established for relay 500 extending over the lower right contact of cam 503, to ground through the normal segment of the brush carriage commutator and brush 557. Relay 500 upon energizing, opens the circuit of the brush carriage magnet 541 and closes a circuit for advancing sequence switch 520 into normal position. This circuit extends from battery through the winding of magnet 520, upper left contact of cam 513, lower left contact of cam 510, right armature and front contact of relay 500 to ground at the left contact of cam 508. A circuit is also closed in parallel therewith for the holding magnet 545 extending through the lower left contact of cam 513 and thence as traced to ground at cam 508. As soon as sequence switch 520 leaves position 18½, relay 500 deenergizes. The circuits of the final selector are now in normal condition.

Had the called line tested busy, then when the sequence switch 520 passed through positions 7 to 7½, relay 262 would have been maintained energized since the circuit previously traced through relay 519 at the final selector would have been maintained in position 9 of sequence switch 520 as previously described. Therefore, when the sequence switch 220 of the first group selector advanced out of position 10½, relay 222 would have been maintained locked over a circuit extending from battery through the lower contacts of cam 223, winding of relay 222, lower right contact of cam 211, left armature and front contact of relay 222, right contacts of cam 232 to ground at the armature and front contact of relay 262. Sequence switch 220 does not therefore, leave position 11 under these conditions. When, therefore, the calling subscriber releases the connection and relay 237 becomes deenergized, the circuit of relay 262 is opened at 130

the armature and front contact of relay 287 and relay 222 therefore becomes unlocked and advances sequence switch 220 into position 12. The circuit of sequence switch 220 5 may be traced from battery through the winding of the sequence switch magnet, lower right contact of cam 206, right armature and back contact of relay 222 to ground at the right contact of cam 205. With the 10 sequence switch in position 12, a circuit is established for relay 209 which may be traced from battery through the winding of relay 209, intermediate right armature and back contact of relay 219, upper contacts of 15 cam 218, lower contact of cam 200 to ground at armature and back contact of relay 237. Relay 209 locks to ground through its inner left armature and front contact and lower right contact of cam 202 and is maintained 20 energized until the sequence switch leaves position 18½. At its outer left armature relay 209 closes a circuit for relay 224 extending from battery at the upper right contact of cam 223 winding of relay 224, 25 outer left armature and front contact of relay 209 to ground at the lower contact of cam 210. Relay 224 locks directly to ground over its inner right armature and is maintained energized until the sequence switch 30 leaves position 16¼. With relay 224 energized, when the sequence switch is passing through positions 13¾ to 16, booster battery is not connected to the sleeve conductor of the calling line over the outer right armature of relay 224 for operating the message register and no registration is effected. 35 From this point, the release of the connection proceeds as previously described.

If the connection was established through 40 to the terminals of the called line and no response received, message registration is prevented and the calling subscriber releases the connection in the manner just described in connection with a call to a busy line.

In the banks of the second group selectors, all trunks leading to offices having an even ten-thousands digit are located in the first, third, fifth, seventh and ninth levels and trunks leading to offices having an odd 50 ten-thousands digit are located in the second, fourth, eighth, and tenth levels. Thus, in the case previously assumed, trunks leading to the office having lines terminating therein numbered 80,000 to 81,999 are connected to the first level. Trunks leading to the office having lines 90,000 to 91,999 terminate in the second level. Trunks terminating in offices having lines 82,000 to 83,999 terminate in the third level, etc. Thus, had the ten-thousands digit been 9 instead of 8 as previously assumed, it would have been necessary to dial a code to set the B register on a terminal cross-connected at the rack 700 to the rack terminal 710. In that case, 60 wiper 814 of the thousands register would

have been employed on the thousands selection and the second group selector would have been operated to the sixth level instead of the fifth to select a line in the 95,000 group. 70

The trunks are connected in a similar manner in the banks of the third group selector. Thus, in the case assumed, the third group selector having access to the section of the exchange in which lines 4,000 to 75 5,999 terminate has its first level connected to trunks corresponding to the group of connectors in which lines 4,000 to 4,199 terminate, its second level to connector switches in which lines 5,000 to 5,199 terminate, the 80 third level to selectors in which lines 4,200 to 4,299 terminate, the fourth level to selectors in which lines 5,300 to 5,399 terminate, the fifth level to selectors in which lines 4,400 to 4,599 terminate, the sixth level to 85 selectors in which lines 5,400 to 5,599 terminate, etc. In the case assumed, the sixth level was selected. Had the thousands digit been even, for example 4, then the fifth level would have been selected in the following 90 manner. With the thousands register in position 4, when the sequence switch 920 passes position 9¼ following the thousands selection, a circuit is established for the No. 1 counting relay extending from battery 95 through the winding of counting relay 927, the armature and back contact of the No. 1' counting relay 928, No. 4 terminal and wiper 811 of the thousands register, to ground at the lower right contact of cam 913 (9¼). When sequence switch 920 reaches position 10 and the fundamental circuit is established for the hundreds selection, the selection is controlled as previously described except that at this time the 100 No. 1 counting relay is already energized and therefore is skipped when the counting relays count down in response to the selective movement of the third group selector 105 450. This results in setting the trip spindle 110 of the third group selector for tripping the brushes having access to the fifth level of the switch rather than to the sixth level.

Provision is made at the A register for 115 making eight B register selections only since there are no letters on the subscriber's dial corresponding to the digits 1 and 0. In order to reduce the number of B registers required the B registers are provided with twenty active terminals in their banks and with two normal positions. If the A register is set into an even position one of the four B registers will be selected and will advance as previously described from the first normal position in response to the dialing of the second or B code digit. If the A register is set into an odd position one of the same four B registers will be selected as before and will at once advance automatically to its second normal position, passing 120 125 130

over the first ten selection positions of its bank, and will then be advanced from such second position in response to the second or B code digit. This arrangement enables 5 eight selections to be made with a single A register and four B registers, thus reducing the number of B registers required by half.

The automatic advance of a selected B register when the A digit is odd is accomplished by the provision of slow acting relay 613, which becomes energized in series with the stepping magnet of the selected B register. For example, if the A register is set into the odd position 3, a circuit is established 10 for the stepping magnet 704 of register B⁴, which may be traced from battery, through the winding of magnet 704, the No. 3 terminal and wiper 611 of register A, the upper left contact of cam 933 (2 to 3), 15 the interrupter contact of stepping magnet 610 of steering switch RS, the upper left and lower right contacts of cam 945, winding of relay 613, wiper 614 and No. 3 contact of register A, first normal terminal and 20 wiper 711 of register B⁴, interrupter contacts of magnets 704, 800, 801, 802 and 803, to ground. Relay 613 upon energizing closes a locking circuit for itself as soon 25 as magnet 704 moves its wipers from its first normal position, and also establishes a 30 stepping circuit for the magnet 704 extending from battery, through the magnet 704, No. 3 terminal and wiper 611 of register A, upper left contact of cam 933, interrupter 35 contact of magnet 610, upper left and lower right contacts of cam 945, winding of relay 613, armature and contact of relay 613, off-normal terminals of the restoring bank and wiper 711 of register B⁴, and thence to 40 ground over the interrupter contacts of magnets 704, 800, 801, 802 and 803. Magnet 704 continues to operate to move its wipers step by step into engagement with their second normal terminals. When this position is 45 reached the circuit before traced for magnet 704 is opened and relay 613 and magnet 704 deenergize, bringing the wipers of the register B⁴ to rest. Relay 613, being slow acting, remains energized during the operation of 50 magnet 704. The wipers of register B⁴ are then moved from their second normal position a number of steps in accordance with the second series of impulses dialled in a manner before described. After this the 55 operation of the sender proceeds as previously described.

Connection to operator's position.—If it is desired to extend a connection to an operator's position (not shown) reached by means 60 of ring-down trunks leading from levels of the first group selector 250, it is necessary to stop the selection at this point, that is, after the setting of the trip spindle of the first group selector. The selected register, 65 for example, B⁴ of the group of registers B¹ to B⁴, will in this case be set to such a position that a circuit is completed upon the energization of the relay 909 in position 2^{3/4} of the sequence switch 920 for the relay 903. This circuit may be traced from ground, 70 winding of relay 903, terminal 713 upon the distributing rack 700, the terminal of the register B⁴ connected thereto, wiper 708, outer left armature and front contact of relay 909, lower right and upper left contacts of cam 933, wiper 611 of register A, and thence to battery through the winding of magnet 704. Relay 903 upon energizing closes a locking circuit for itself extending 75 from its inner right armature and front contact to battery at the upper left contact of cam 918, whereby the relay 903 is maintained energized until the sequence switch 920 leaves position 8. The trip spindle of the first group selector operates in the manner before described to cause the sender stepping relay 901 to be intermittently short-circuited and the counting relays to energize and lock up in pairs, one pair for each step 80 of the trip spindle. This selection takes 85 place with sequence switch 920 in position 6, the sequence switch being driven into position 8 in the manner before described upon the energization of the last counting relay 930 in the chain of counting relays. 90

As the call to an operator's position is reached by ring-down trunks from certain levels of the first group selector, no further selecting operations are required to be controlled by the register sender. Under these 100 circumstances the energization of relay 903 causes the sequence switch 920 to be driven from position 8 into position 10 over a circuit which may be traced from battery, through the winding of sequence switch 105 magnet 920, the outer right armature and front contact of relay 903, the upper contact of cam 925 (8), the armature and front contact of stepping relay 901, thence to ground at the lower right contact of cam 911. This circuit is closed as soon as the 110 sender stepping relay 901 energizes in the fundamental circuit after the trip spindle selection at the first group selector has been completed. In position 10 a circuit is closed 115 for the sequence switch 920, which may be traced from battery, through the magnet 920, the upper right contact of cam 912 (10 to 14), wiper 615 of the register steering switch RS in position 2, to ground at the 120 armature and back contact of relay 935. The sequence switch is driven by means of this circuit out of position 10 into position 15. In this position relay 909 is again energized and the steering switch RS returned to normal, after which the register B⁴ and the sequence switch are restored in the manner previously described. 125

It has been explained that the relay 917 is operated upon all calls in which the se- 130

lected register of the registers B¹ to B⁴ is set to a position indicating a connection which actually exists. If a subscriber sets up a non-existing connection upon the registers, it is desirable that his call be extended to a monitoring operator's position, who will be able to give him the necessary information to enable him to extend the desired connection correctly. For this purpose the back contacts of the outer left and inner right armatures of relay 917 are connected to terminals 714 and 715 upon the interconnecting rack 700, and these rack terminals are then connected to counting relay 917 leads in such a manner as to obtain the operation of the selector switch as will extend the calling line to the monitoring operator's position. In the system disclosed two selectors are assumed to be necessary to extend a connection of this character. The trip spindles of the first group selector 250 and of a third local group selector (not shown) must be set to select an operator's position connected to terminals of the selected level of the third group selector switch. The trip spindle of the first group selector 250 is set in position 6 of the sequence switch 920 under the control of the counting relays, commencing at the counting relay connected at the interconnecting rack 700 to the terminal 715. This counting relay circuit may be traced in part from battery, through the required counting relay, over the counting relay lead associated with such counting relay, the cross-connection from the counting relay lead to the rack terminal 715, the inner right armature and back contact of relay 917, the lower left contact of cam 925 (5 $\frac{3}{4}$ to 6), the armature and front contact of stepping relay 901, thence to ground at the lower right contact of cam 911. The second selection, that is, the setting of the trip spindle of the selected third group selector is controlled by the counting relays commencing at the counting relay connected at the interconnecting rack 700 to the terminal 714. The counting relay circuit for this selection may be traced in part from battery, through the required counting relay, over the counting relay lead connected thereto, terminal 714, the outer left armature and back contact of relay 917, the outer left armature and front contact of relay 938, relay 938 being operated at this time, the outer right armature and back contact of relay 903, the upper contact of cam 925 (8), the armature and front contact of relay 901, to ground at the lower right contact of cam 911. In this way the proper set of brushes of the selected third group selector is selected and then hunt over the contacts in the selected level until an idle operator's position is reached. The register sender is then released.

Should the subscriber desire to extend a connection to the monitoring operator, he may do so by removing his receiver, and after receiving the dialing tone dial the digit zero, thereby transmitting ten impulses to the A register so that the latter moves its wipers ten steps from normal into engagement with its No. 10 terminals. A circuit is now closed for relay 942, which may be traced from battery, winding of relay 942, the No. 10 terminal engaged by brush 611 of register A, the upper left contact of cam 933, the interrupter contacts of magnets 610, the upper left and lower right contacts of cam 945, winding of relay 613, wiper 614 of register A, and to ground on the No. 10 terminal engaged by this wiper. Relay 942 upon energizing closes a circuit for relay 909 extending from battery, through the winding of relay 909, the inner right armature and front contact of relay 942, thence as previously traced over cam 933, to ground at the wiper 611 and the No. 10 contact upon which it is standing. Relay 909 upon energizing closes a circuit for advancing sequence switch 920 out of position 2 into position 5, which may be traced from battery, through the magnet winding of sequence switch 920, the lower right contact of cam 912, the outer right armature and front contact of relay 909, to ground at the upper right contact of cam 913. In position 5 a circuit is closed for advancing the sequence switch into position 6, which may be traced from battery, through the magnet winding of sequence switch 920, the upper left contact of cam 912, the outer left armature and back contact of relay 921, and to ground at the upper right contact of cam 913. In position 6 the trip spindle of the first group selector is set under the control of the counting relays commencing at the counting relay connected at the distributing rack to terminal 715, the sender stepping relay 901 being short-circuited in the usual manner at each step taken by the trip spindle to cause the counting relays to operate and lock up in pairs, one pair for each step.

Upon the energization of the last counting relay 930, a circuit is closed for driving sequence switch 930 into position 8, which circuit may be traced from battery, through the magnet winding 920, the upper left contact of cam 912, the outer left armature and back contact of relay 921, the left armature and back contact of relay 931, to ground at the left armature and front contact of relay 930. With sequence switch 920 in position 8, the trip spindle of the selected third group selector is set under the control of the counting relays commencing at the counting relay connected at the distributing rack to the terminal 714. In this manner the connection is extended to the monitoring operator's position, connected to terminals in the selected level of the third group selector.

It may be desired to control the setting of the call indicator equipment from the registering mechanism so as to inform an operator, at whose position the call indicating equipment is installed, of the designation of a desired line. In the system illustrated, the register B¹ has been set aside for calls of this character. However, as this register may also be used for calls to ring-
 10 down trunks, when it would be selected by the A register in response to the dialing of the first digit 8, it is necessary to provide some kind of discriminating means for discriminating between calls of the two characters. This is accomplished by means of relays 716, 717 and 718. The relay 718 is energized if the first digit dialed is 1, in response to which the wipers of the register A are moved into engagement with the No. 1 terminals. The circuit of relay 718 may be traced from battery, winding of stepping magnet 701, wiper 611 of register A and the No. 1 terminal upon which it is resting, the upper left contact of cam 933, the inter-
 20 rupter contacts of magnet 610, the upper left and lower right contacts of cam 945, winding of relay 613, wiper 614 of register A and the No. 1 terminal upon which it is resting, winding of relay 718 to ground.
 25 Relay 718 energizes in this circuit and closes a locking circuit for itself extending from ground, through its winding, its outer left armature and front contact, to battery at the upper left contacts of cam 918 (1 $\frac{3}{4}$ to 8).
 30 Relay 718 upon energizing also connects up the No. 1, No. 5 and No. 0 counting relay leads to the correspondingly numbered terminals of the lowermost bank of register B¹. If then the second code digit, which will
 35 operate the register B¹, is 1, 5 or 0, the selection will be controlled beginning with the first, fifth or zero counting relay. If, on the other hand, the second digit dialled is not one of these numbers, then relay 917, which
 40 otherwise is energized in series with the counting relays, will not be energized in the manner before described and the connection will be extended to the monitoring operator.
 45 If the first or A code digit is 8, the relay 717 would be energized in a circuit extending from ground, through its winding, wiper 614 of register A and the No. 8 terminal upon which it is resting, winding of relay 613, thence as previously traced to battery through the winding of stepping magnet 701. Relay 717 upon energizing closes a locking circuit for itself extending from ground, over its outer left armature and front contact, winding of relay 716, to battery at the upper left contact of cam 918.
 50 Relays 716 and 717, both being energized, connect up counting relay leads 2, 3, 4, 6, 7, 8 and 9 to the correspondingly numbered terminals in the lowermost bank of register
 55 B¹, so that if the second digit dialled is one of these numbers, then the call progresses normally. If, however, the second digit dialled is 1, 5 or 0, the relay 917 is not energized and the call is directed to the monitoring operator in the manner hereinbefore described.
 60

On calls involving the energization of either relay 935 or 903, the first when a full mechanical connection is being established, 75 and the latter when a connection is being established to an operator's position, it may be desirable to prevent metering. This may be accomplished through the provision of relay 719, which is energized in series with either relay 935 or 903, depending upon whether the terminals 720 and 721 of the interconnecting rack are employed instead of the terminals 706 and 713. If the relay 719 is included in the circuit of either relay 80 903 or relay 935, a circuit is established from ground at the armature and front contact of relay 719, over the lower left contact of cam 131, the left contacts of cam 226, winding of relay 224, to battery through the upper right and lower left contacts of cam 223, and relay 224 energizes and locks. When, therefore, upon the release of the established connection, the sequence switch 220 of the first group selector passes through 95 the message registering positions 14 to 16, inclusive, registration is prevented in the manner hereinbefore described.
 100 Should the calling subscriber restore his receiver to the switchhook before the completion of the connection, relays 906 and 908 will become deenergized and the sequence switch of the sender will be driven from the position in which it is standing. If the release occurs before relay 935 is 105 energized, that is, prior to moving into position 8, the sequence switch 920 is driven from the position in which it is standing into position 10 by means of a circuit which may be traced from battery, through the magnet winding of switch 920, the upper contact of cam 936 (2 to 8), the outer right armature and back contact of relay 942, to ground at the armature and back contact 110 of relay 906. Upon reaching position 10 it is then advanced into position 15 over a circuit which may be traced from battery, through the magnet winding of switch 920, the upper right contact of cam 912 (10 to 14), the inner right armature and back contact of relay 908, thence to ground at the armature and back contact of relay 935. If the sequence switch is standing in an advanced position when the release occurs, 115 a circuit is completed for the sequence switch magnet 920 over the upper left contact of cam 912, outer left armature and front contact of relay 921, thence to ground at the armature and back contact of relay 906. The sequence switch 920 advances 120 125 130

through positions 8, 10, 12 and 14 under the control of this circuit and comes to rest in position 15. From this point the sender releases as previously described. As the 5 release of the selectors which may have been operated at the time premature release occurs does not involve any features of the present invention, a description thereof will not be made herein.

10 What is claimed is:

1. In a telephone exchange system, a calling line, selector switches for extending a connection from said calling line, a registering mechanism for controlling said switches, 15 said mechanism comprising a primary register and a plurality of secondary registers, means under the control of the calling subscriber for setting said registers to record digits of the designation of a desired connection, and means whereby any one of said secondary registers may be selected directly through the operation of said primary register.

2. In a telephone exchange system, a calling line, selector switches for extending a connection from said calling line, a registering mechanism for controlling said switches, said mechanism comprising a primary register and a plurality of secondary registers, 30 means under the control of the calling subscriber for setting said registers to record digits of the designation of a desired connection, and means whereby any one of said secondary registers may be directly selected 35 in response to the operation of said primary register upon the dialing of the first digit of the designation and whereby said selected secondary register is thereupon operated in response to the second digit dialled.

3. In a telephone exchange system, a calling line, selector switches for extending a connection from said calling line, a plurality of registering mechanisms for controlling said switches, means for selecting an idle one of said mechanisms, each of said mechanisms comprising a primary and a plurality of secondary registers, means under the control of the calling subscriber for setting said registers to record digits of the designation of a desired connection, and means whereby any one of said secondary registers may be directly selected through the operation of said primary register.

4. In a telephone exchange system, a calling line, a link circuit and selector switches for extending a connection from said calling line a plurality of registering mechanisms, each comprising a primary and a plurality of secondary registers, means for associating an idle registering mechanism with said link circuit, means under the control of the calling subscriber for setting said registers to record digits of the designation of a desired connection, and means whereby any one of said secondary registers may be

directly selected through the operation of said primary register.

5. In a telephone exchange system, a calling line, selector switches for extending a connection from said calling line, a registering mechanism for controlling said switches, said mechanism comprising a primary register and a plurality of secondary registers, means under the control of the calling subscriber for setting said registers to record digits of the designation of a desired connection, means whereby any one of said secondary registers may be selected in response to the operation of said primary register, and means for giving the selected secondary register an arbitrary setting dependent upon the set position of said primary register.

6. In a telephone exchange system, a calling line, selector switches for extending a connection from said calling line, a registering mechanism for controlling said switches, said mechanism comprising a primary register and a plurality of secondary registers, means under the control of the calling subscriber for setting said registers to record digits of the designation of a desired connection, means whereby any one of said secondary registers may be selected in response to the operation of said primary register, means for giving the selected register an arbitrary setting dependent upon the set position of said primary register, and means thereafter effective for further setting said selected register in response to the second digit dialled.

7. In a telephone exchange system, a calling line, selector switches for extending a connection from said calling line, a registering mechanism for controlling said switches, 105 said mechanism comprising a primary register and a plurality of secondary registers, means under the control of the calling subscriber for setting said registers to record digits of the designation of a desired connection, means whereby any one of said secondary registers may be selected in response to the operation of said primary register, means for giving the selected register an arbitrary setting dependent upon whether 110 the primary register is set into an odd or even position, and means thereafter effective for further setting said selected register in response to the second digit dialled.

8. In a telephone exchange system, a calling line, selector switches for extending a connection from said calling line, a registering mechanism for controlling said switches, said mechanism comprising a primary register and a plurality of secondary 125 registers, each of said secondary registers having a plurality of normal positions from which it may be moved to record the second digit of a desired connection, means under the control of the calling subscriber for set- 130

- ting said registers to record digits of the designation of a desired connection, means whereby any one of said secondary registers may be selected in response to the operation of said primary register, means for moving the selected register from one of said normal positions to the next normal position dependent upon the set position of the primary register, and means thereafter effective for advancing said selected register from the normal position in which it is standing in response to the second digit dialled.
9. In a telephone exchange system, a calling line, selector switches for extending a connection from said calling line, a registering mechanism for controlling said switches, said mechanism comprising a primary register and a plurality of secondary registers, each of said secondary registers having its bank terminals divided into two groups, means under the control of the calling subscriber for setting said registers to record digits of the designation of a desired connection, means whereby any one of said secondary registers may be selected in response to the operation of said primary register, means for advancing the wipers of the selected secondary register over the first group of terminals if said primary register is set in a certain position, and means thereafter effective for advancing the wipers of the selected register over the second group of terminals in response to the second digit dialled.
10. In a telephone exchange system, a calling line, selector switches for extending a connection from said calling line, a registering mechanism for controlling said switches, said mechanism comprising a primary register, a plurality of secondary registers and an impulse controlling device, means under the control of the calling subscriber for setting said registers to record digits of the designation of a desired connection, means whereby any one of said secondary registers may be selected through the operation of said primary register, and means for cross-connecting the terminals of said secondary registers with said impulse controlling device whereby the control of said switches by said device may be readily changed.
11. In a telephone exchange system, a calling line, selector switches for extending a connection from said calling line, a registering mechanism for controlling said switches, said mechanism comprising a primary register, a plurality of secondary registers and an impulse controlling device, means under the control of the calling subscriber for setting said registers to record digits of the designation of a desired connection, means whereby any one of said secondary registers may be selected through the operation of said primary registers, and
- 5 a cross-connecting rack interposed between said registers and said impulse controlling device whereby the control of said switches by said device may be readily changed.
12. In a telephone exchange system, a calling line, selector switches for extending a connection from said calling line, a registering mechanism for controlling said switches, said mechanism comprising a primary register, a plurality of secondary registers and an impulse controlling device, means under the control of the calling subscriber for setting said registers to record digits of the designation of a desired connection, means whereby any one of said secondary registers may be selected through the operation of said primary register, means for curtailing the operation of said impulse controlling device if the designation recorded is such as to necessitate a lesser number of switching stages in the control of said switches than said mechanism is normally capable of, and a cross-connecting rack interposed between said last named means and said registers whereby the control of said means may be readily changed.
13. In a telephone exchange system, a calling line, selector switches for extending a connection from said line, a registering mechanism for controlling said switches, said mechanism comprising a primary register and a plurality of secondary registers, means under the control of the calling subscriber for setting said registers to record digits of the designation of a desired connection, means whereby any one of said secondary registers may be selected through the operation of said primary register, and means associated with one of said secondary registers and controlled directly by said primary register for discriminating between settings of said secondary register.
14. In a telephone exchange system, a calling line, selector switches for extending a connection from said line, a registering mechanism for controlling said switches, said mechanism comprising a primary register and a plurality of secondary registers, means under the control of the calling subscriber for setting said registers to record digits of the designation of a desired connection, means whereby any one of said secondary registers may be selected through the operation of said primary register, and relay means associated with one of said secondary registers and controlled directly by said primary register for discriminating between settings of said secondary register.
15. In a telephone exchange system, a calling line, selector switches for extending a connection from said calling line, a registering mechanism for controlling said switches, said mechanism comprising a plurality of registers and an impulse controlling device, means under the control of

the calling subscriber for setting said registers to record digits of desired connections, a cross-connecting rack interposed between said registers and said impulse controlling device, and means for connecting terminals of said registers corresponding to non-existing offices of the exchange to said rack

whereby connections attempted to such non-existent offices are routed to an operator's position.

10

In witness whereof, I hereunto subscribe my name this 23 day of May A. D., 1923.

LIPA POLINKOWSKY.

DISCLAIMER.

1,541,388.—*Lipa Polinkowsky*, Antwerp, Belgium. AUTOMATIC TELEPHONE-EX-
CHANGE SYSTEM. Patent dated June 9, 1925. Disclaimer filed August 30, 1927,
by the patentee, assignee *Western Electric Company, Incorporated*, consenting.

Hereby enters this disclaimer to the said claims of said Letters Patent which are
in the following words, to wit:

“1. In a telephone exchange system, a calling line, selector switches for extending
a connection from said calling line, a registering mechanism for controlling said
switches, said mechanism comprising a primary register and a plurality of secondary
registers, means under the control of the calling subscriber for setting said registers
to record digits of the designation of a desired connection, and means whereby any
one of said secondary registers may be selected directly through the operation of said
primary register.

“2. In a telephone exchange system, a calling line, selector switches for extending
a connection from said calling line, a registering mechanism for controlling said
switches, said mechanism comprising a primary register and a plurality of secondary
registers, means under the control of the calling subscriber for setting said registers
to record digits of the designation of a desired connection, and means whereby any
one of said secondary registers may be directly selected in response to the operation of
the primary register upon the dialing of the first digit of the designation and
whereby said selected secondary register is thereupon operated in response to the
second digit dialed.

“3. In a telephone exchange system, a calling line, selector switches for extending
a connection from said calling line, a plurality of registering mechanisms for con-
trolling said switches, means for selecting an idle one of said mechanisms, each of
said mechanisms comprising a primary and a plurality of secondary registers, means
under the control of the calling subscriber for setting said registers to record digits
of the designation of a desired connection, and means whereby any one of said
secondary registers may be directly selected through the operation of said primary
register.

“4. In a telephone exchange system, a calling line, a link circuit and selector
switches for extending a connection from said calling line, a plurality of registering
mechanisms, each comprising a primary and a plurality of secondary registers,
means for associating an idle registering mechanism with said link circuit, means
under the control of the calling subscriber for setting said registers to record digits
of the designation of a desired connection, and means whereby any one of said
secondary registers may be directly selected through the operation of said primary
register.”

“10. In a telephone exchange system, a calling line, selector switches for extending
a connection from said calling line, a registering mechanism for controlling said
switches, said mechanism comprising a primary register, a plurality of secondary
registers and an impulse controlling device, means under the control of the calling
subscriber for setting said registers to record digits of the designation of a desired
connection, means whereby any one of said secondary registers may be selected
through the operation of said primary register, and means for cross-connecting the
terminals of said secondary registers with said impulse controlling device whereby
the control of said switches by said device may be readily changed.

“11. In a telephone exchange system, a calling line, selector switches for extending
a connection from said calling line, a registering mechanism for controlling said
switches, said mechanism comprising a primary register, a plurality of secondary
registers and an impulse controlling device, means under the control of the calling
subscriber for setting said registers to record digits of the designation of a desired
connection, means whereby any one of said secondary registers may be selected
through the operation of said primary registers, and a cross-connecting rack inter-
posed between said registers and said impulse controlling device whereby the control
of said switches by said device may be readily changed.

“12. In a telephone exchange system, a calling line, selector switches for extending
a connection from said calling line, a registering mechanism for controlling said
switches, said mechanism comprising a primary register, a plurality of secondary

registers and an impulse controlling device, means under the control of the calling subscriber for setting said registers to record digits of the designation of a desired connection, means whereby any one of said secondary registers may be selected through the operation of said primary register, means for curtailing the operation of said impulse controlling device if the designation recorded is such as to necessitate a lesser number of switching stages in the control of said switches than said mechanism is normally capable of, and a cross-connecting rack interposed between said last named means and said registers whereby the control of said means may be readily changed."

"15. In a telephone exchange system, a calling line, selector switches for extending a connection from said calling line, a registering mechanism for controlling said switches, said mechanism comprising a plurality of registers and an impulse controlling device, means under the control of the calling subscriber for setting said registers to record digits of desired connections, a cross-connecting rack interposed between said registers and said impulse controlling device, and means of connecting terminals of said registers corresponding to non-existing offices of the exchange to said rack whereby connections attempted to such non-existent offices are routed to an operator's position."
